UNITED STATES PATENT OFFICE.

SEDWICK N. WIGHT, OF GATES, NEW YORK, ASSIGNOR TO GENERAL RAILWAY SIGNAL COMPANY, OF GATES, NEW YORK, A CORPORATION OF NEW YORK.

ABSOLUTE PERMISSIVE BLOCK-SIGNAL SYSTEM.

1,294,736.

Specification of Letters Patent. Patented Feb. 18, 1919.

Application filed March 13, 1913, Serial No. 753,892. Renewed May 28, 1918. Serial No. 237,118.

To all whom it may concern:

Be it known that I, SEDGWICK N. WIGHT, a citizen of the United States, and a resident of the town of Gates, in the county of Monroe and State of New York, have invented a new and useful Absolute Permissive Block-Signal System, of which the following is a specification.

The objects of the present invention are to provide a system of electric signaling for single track railways by which: first, a train which enters upon and moves in a certain direction upon a piece of single track between two passing sidings will prevent the entrance of a train moving in an opposite direction upon the same piece of single track; second, with the same number of signals between sidings as are used in the best approved single track signaling of the present day, there may exist a very much less spacing distance for trains running under caution signals and much less spacing distance for trains running under proceed signals; third, no head-on flagging, with the consequent delay, will be needed; fourth, a much greater reliability of the distant signal indication will be obtained than is now obtained in the best approved single track signaling system heretofore known; fifth, equal or greater facility for train movements than is possible by means of the best approved single track signaling systems heretofore known; sixth, the results to be accomplished by means of apparatus constructed on exactly the same principles as is the apparatus now being used in the best approved single track signaling system.

Other objects and advantages will appear as the description of the invention progresses, and the novel features of the invention will be particularly pointed out in the appended claims.

The system herein shown and described is one made possible by the invention of Wilmer W. Salmon and Frank L. Dodgson, known as the "Absolute permissive block signal system," disclosed in Reissue Patent No. 14,326. One great merit of the Salmon and Dodgson invention lies in the fact that two signaling circuits may be employed, one, opened by the presence of a train on any part of a certain track circuit section, the other, closed only by the entrance of a train from a predetermined direction upon the

same section, and the apparatus for accomplishing such result is the ordinary, well known, thoroughly tested and approved apparatus such as is now universally used in railway automatic block signaling. 55

In describing the invention in detail, reference is had to the accompanying drawing, wherein I have illustrated a preferred physical embodiment of my invention, and wherein like characters of reference designate corresponding parts throughout the several 60 views and in which:

Figure 1, is a schematic view of a section of track, signals for controlling the movement of trains over the track, and the necessary apparatus and electrical circuits needed to accomplish the objects of applicant's invention; Fig. 2, is a schematic view similar to Fig. 1 and is a continuation thereof; Fig. 3, is a schematic view similar to Fig. 1 and is a continuation of Fig. 2; Fig. 4, 75 is a schematic view similar to Fig. 1, and is a continuation of Fig. 3.

The drawings when placed in proper order end to end, represent a continuous line of single track composed of rails 17 and 18, 80 having two through passing sidings A and B connected thereto, arranged parallel thereto and connected in the usual manner to the line of single track by switches 19, 19', 19² and 19³. 85

The section of track between the left hand end of Fig. 1 and the left hand end of passing siding A, has been designated by C. The section of track coextensive with the passing siding A, has been designated A¹. The section of track from the right hand end of passing siding A to the left hand end of passing siding B, has been designated D. The section of track coextensive with passing siding B has been designated B¹ and B². The section of trackway from the right hand end of passing siding B to the right hand end of Fig. 4, has been designated E. 90 95

The amount of trackway taken for illustration and the number of signals shown, is such that two complete single track blocks have been illustrated; namely, D, and C and E, which together are of such length that they are equal to the length of section D. 100 The illustration thus allows one to consider section C as a continuation of section E, or, vice versa, that section E is the beginning of 105

section C, so that as the description progresses and it is assumed that a train moving toward the right passes upon section C it may be considered that the train has just 5 left section E and when it is later assumed that a train moving toward the right passes off from section E, that it then passes upon section C.

The trackway, within the sections, is further divided by insulating joints 20 into separate, closed circuited track circuit sections, each containing a battery 21 connected across the rails at one end of the section and relays as 22, 23, 24, 25, 26, 27, 28, 15 29, 30, 31, 32, 33, 34, 35 and 36 connected across the rails at the opposite end of the section. The operation of the track relays 22 to 36 inclusive, by the passage of a train, onto and over a closed track circuit section 20 is identical with the known operation of such track relays as extensively used, and therefore does not merit further discussion or explanation.

The movement of trains over the trackway in an easterly direction or toward the right of the figures, is governed by signals 1 to 8 inclusive. The movement of trains over the trackway in a westerly direction or toward the left of the figures, is governed by 25 signals 9 to 16 inclusive.

Signals 1 to 16 inclusive may be of any of the well known and approved types as used either in single track signaling or double track signaling at the present day, that is, 35 they should consist fundamentally of an operating motor of any of the well known types such as compressed air, carbonic acid gas, or electricity for moving the semaphore arm from its biased position to an operated 40 position, known ordinarily as the caution position, and to another operated position, known ordinarily as the proceed position, and should furthermore each contain means which become operative upon the proper 45 placing of the semaphore in either of its operated positions to retain it in such position, together with typical circuit controllers operated in conjunction with the movement of the semaphore to control the various operating and holding circuits.

Although applicant has chosen to herein show a three-position signal in this particular embodiment of his invention, it is to be understood that he does not intend to exclude 55 the use of the well known equivalents of a three-position signal because it is well known and understood by those skilled in this art that the same operating wires used for controlling a three-position signal may, 60 for instance, be used equally as well for controlling two, two-position semaphore arms placed upon the same pole, or on separate poles, and it is further well known and understood by those skilled in the signaling 65 art that two, two-position semaphore arms

as ordinarily used impart exactly the same signaling information as does one three-position semaphore arm.

Each signal mechanism has one or more circuit controllers operated thereby. These 70 circuit controllers have been represented schematically as conducting arms 37, 38, 39, 40, 41, 42, 43, 44, 45, 46, 47, 48, 49, 50, 51, 52, 53, 54, 55 and 56. Each of the conducting circuit controller arms 37 to 56 inclusive is 75 operated by that signal mechanism adjacent to which it is located upon the drawings and is assumed to be in the position shown on the drawings when the signal adjacent to which it is placed on the drawings, is in the 80 position as shown upon the drawings, and is further considered to be moved from the illustrated position to the dotted line position, indicated, upon a movement of the signal to the caution position and the danger 85 position respectively. Arcs of varying length are struck concentric with the arc describing end of the conducting circuit controller arm and by their varying length indicate the extent of rotative movement of 90 conducting circuit controller arms during which they are in contact with metallic strips assumed to be located in a position identical with the small arcs shown.

Each signal 1 to 16 inclusive has associated therewith and located adjacent thereto and in ordinary practice supported by the same pole which supports the signals, what are known as control relays 57, 58, 59, 60, 61, 62, 63, 64, 65, 66, 67, 68, 69, 70, 71 and 72. 100 Each of these control relays is included in a governing circuit hereinafter to be described.

Associated with each signal directly governing entrance to and movement over the single track section C, D and E, are what is 105 known as stick relays 73, 74, 75, 76, 77, 78, 79, 80, 81, 82, 83 and 84. Each of the stick relays 73 to 84 inclusive is included in one or more governing circuits to be hereinafter described and each of the stick relays 73 to 110 84 inclusive is operated and controlled in the manner of the well known stick relay.

Certain of the signals as 2, 14, 6 and 10 do not have a stick relay directly associated therewith, but have instead pole changing 115 relays as 85, 86, 87 and 88.

Although applicant has herein designated certain relays as track relays, certain others as control relays, certain others as stick relays and certain others as neutral relays, it 120 is not to be inferred from such distinctive designating terms that there is in reality any essential or fundamental difference in the relays so designated, because all of the relays are essentially of the well known and 125 ordinary type used for signaling purposes and vary not because of difference of internal construction, but rather because of the uses to which they are put, with the exception, however, that the control relays 57 to 130

- 72 inclusive are constructed exactly like the other relays enumerated but have in addition a polarized armature designated in the several relays by 89, 90, 91, 92, 93, 94, 95, 96, 97, 5 98, 99, 100, 101, 102, 103 and 104, which is operated by the same operative coils as used in each of the relays to operate their armatures and which stands in a position represented by a vertical position on the drawings, when the current flowing through the coils, is in one direction, but which has its lower end moved to the left upon a flow of current through the coils of the relay in an opposite direction.
- 10 15 Each of the signals directly governing movements of trains onto or over the single track sections C, D and E, have connected therewith a pole changing switch of the ordinary form which has been illustrated on the drawings in the ordinary manner and designated by the numeral applied to the signal which governs it, with the addition of a superior as 16¹, 1¹, 15¹, 3¹, 13¹, 4¹, 12¹, 20 5¹, 11¹, 7¹, 9¹ and 8¹. Each of the pole changing switches are operated by the mechanism which operates the semaphore of the signal to which it is attached and is in the position as shown upon the drawings when the signals are in the position as shown upon 25 the drawings and remains in such position even after the respective signals move to the caution position, but upon a movement of the signal controlling a pole changing switch to a position below the caution position, then the switch is thrown instantly to the full extreme of its other position as shown in dotted lines upon the drawings, and remains in such thrown position while the signal is in any position below the caution 30 position. When the signal moves from the biased or danger position toward the caution position, each of the pole-changing switches remains in the dotted line position until the signal reaches the caution position 35 40 45 in its upward movement, whereupon the pole-changing switch is instantly thrown to the position as shown in full lines upon the drawings and remains in such position during any further upward movement of the signal toward and in the proceed position.
- 50 At suitable positions along the single track which has been illustrated, suitable sources of current supply have been placed such as 105, 106, 107, 108, 369, 109, 110, 111, 55 112, 113, 114, 115, 116, 117, 118 and 119. In the drawings the sources of current supply have been illustrated as batteries, but it is to be understood that such illustration by no means precludes the use of any suitable 60 65 70 source of current supply, nor is it to be considered to preclude the use of other arrangements of current supply because it is well understood by those skilled in the signaling art that the electric current which must be supplied to a system as shown by appli-
- cant's drawings, may be supplied not only by a single source located as shown upon the drawings, but by full equivalents thereof, which are known to include the use of one source of electric current supply at a point where two signals are located, one governing the movement of trains in one direction and located on one side of the track and another governing movements of trains in an opposite direction and located on the other side of the track. It will be apparent to those skilled in the signal art without further explanation, that the several relays illustrated control armatures which are schematically illustrated in the conventional manner and that the relay armatures act as circuit controllers to close certain circuits when the relay is energized or to close certain circuits when the relay is deenergized or both, as is well understood by those skilled in this art.
- In order to explain the operation of the system which applicant has illustrated, it will be supposed that a train moving in an easterly direction, that is, toward the right of the figures, enters upon track circuit section C¹. If the train considered, so enters track circuit section C¹, it may be considered that it does so by leaving track circuit section E² and as will be more fully understood after a complete reading of this description, but which will necessarily have to be assumed to be true at the present, the signal 16 would then be in the danger position, but even if signal 16 was not then in danger position, it would be placed in the danger position by the entrance of the train to track circuit section C¹, because the entrance of the train to track circuit section C¹ would shunt the relay 22 and would thereby cause the control relay 57 to be deenergized, thus breaking the circuits controlling both the caution and the proceed aspects of signal 16. The details of the operation would be as follows: The train entering upon track circuit section C¹ would cause armature 120 to fall thereby breaking the circuit which is shown existing between wire 121 and wire 122, and it will be further seen that wire 122 is the only means shown for completing one side of the circuit to control relay 57, consequently, irrespective of what causes a flow of current through control relay 57, the dropping of armature 120 would cause the flow of current to cease through the control relay 57. The deenergization of control relay 57 would cause armature 123 to fall, but would not affect the position of polarized armature 89. Upon the dropping of armature 123, the only path by which signal 16 can derive current from battery 105 would be broken, because the current flows from battery 105 to signal 16 in the following path: positive terminal of battery 105, wires 124, 125 and 126, armature 123 then to wire 120.

127, from whence it flows in two paths, one by means of wire 128, polarized armature 89 and wire 129 to signal 16, and returns by means of wires 130, 131 and 132 to the negative terminal of battery 105, the other from wire 127 by means of wire 211 to signal 16, whence it returns by means of wires 130, 131, and 132 to the negative terminal of battery 105. The dropping of armature 123
 10 breaks the continuity of both of the circuits, so that current cannot flow through the proceed control wire 129 or the caution control wire 211, consequently the signal will assume the full bias or danger position. The
 15 condition of the several parts heretofore described as being operated, will remain in the positions as just described just so long as the train remains upon the rails of track circuit section C¹.
 20 The entrance of the train in its forward movement onto the rails of track circuit section C² will in a similar manner cause a deenergization of track relay 23, a dropping of armature 133, a consequent deenergization
 25 of control relay 58 and a dropping of armature 134, which controls the caution and proceed positions of signal 1 just as relay armature 123 controls the caution and proceed positions of signal 16. The entrance
 30 of a train upon track circuit section C² moving in the direction assumed, causes a further operation which it did not cause when it entered track circuit section C¹. This further operation is a preliminary and main-
 35 tained energization of stick relay 74. The preliminary and maintained energization of stick relay 74 depends in the physical embodiment of applicant's invention shown, primarily upon the fact that at the time the
 40 train considered, entered track circuit section C², the signal 1 was in the proceed position and consequently, conducting circuit controller arm 38 was in the position as shown in the drawing, making electrical con-
 45 tact with the arc shaped metallic strip 135. Upon the entrance of the train upon track circuit section C², as has heretofore been pointed out, the track relay 23 was shunted and not only armature 133, but armature 136
 50 dropped, so that a circuit was formed in which current flowed as follows: positive terminal of battery 106, wires 141 and 137, conducting circuit controller arm 38, metallic strip 135, wire 138, armature 136, wires
 55 139 and 149, stick relay 74, wires 140, 142, and 143, to the negative terminal of the bat-
 60 tery 106. The flow of current in the just above traced path causes an energization of relay 74 and thereby causes armature 144 to be raised to its upper position. It should be noticed that current in the circuit just above traced would only flow momentarily because upon the dropping of armature 134 the circuit of both of the control wires for
 65 signal 1 would be broken, consequently, the

signal would start to move to the biased position and in doing so the conducting circuit controller arm 38 would move over metallic strip 135 and before the arm reached the full danger position would break contact with metallic strip 135 thereby breaking the above traced circuit, but, the above traced circuit would not be broken however, until armature 144 had been raised because armature 136 is much quicker in its movement than the arm of signal 1, due to the inertia of the parts of the mechanism connected with signal 1.

A train occupying track circuit section C² causes a deenergization of control relay 58 and a consequent dropping of armature 134, and the armature 144 being now in the raised position a circuit would be completed in which current flows as follows: positive terminal of battery 106, wires 141, 145 and 146, 85 armature 134, wire 147, armature 144, wires 148 and 149, stick relay 74, wires 140, 142 and 143 to the negative terminal of the battery 106. It will be noticed that the circuit last above traced is independent of the position of conducting circuit controller arm 38 and furthermore, that it will remain completed just so long as the train considered remains upon the rails of track circuit section C², because just so long as a train re- 95 mains upon the rails of track circuit section C², the control relay 58 will be deenergized and armature 134 will be in its lower position making contact with wire 147.

The energization of relay 74 causes armature 150 to be raised and remembering that the movement of the signal 1 to the full danger position causes pole changing switch 1¹ to move to the dotted line position, will complete a circuit in which current flows as follows: positive terminal of battery 106, wires 141, 145 and 151, pole changing switch arm 152, in the dotted line position, wires 153, 154, 155, 156 and 157 to wire 158, as it has heretofore been pointed out that section E 110 may be considered as the beginning of section C, then by wires 159 and 160, control relay 72, wire 161, armature 162, wire 163 to wire 164, as it has heretofore been pointed out that section C may be considered as the 115 continuation of section E, then by means of armature 165, which is in the upper position, as soon as all of the train which has been considered gets upon the track circuit section C², then by wire 166 to armature 167, which 120 is in the lower position as shown because stick relay 73 as heretofore stated was not preliminarily energized and maintained energized by the entrance of a train upon track circuit section C¹, the reason for which will 125 appear later, but at present it must suffice to say that a stick relay which is preliminarily energized by a circuit completed through a circuit breaker on a signal governing movements in a direction opposite to the move- 130

ment of a given train, is not preliminarily energized nor maintained energized by the entrance of such train upon the track circuit section governed by the signal, and in this case relay 73 is such a relay, therefore, the armature 167 being in the lower position as shown, the current flows to wires 168, and 169 to armature 150, which in the manner heretofore pointed out and explained, was raised to the upper position and maintained in the upper position similarly to armature 144, so that the current flow continues to wires 170, 171, and 172 to arm 173 of the pole changing switch 1¹, which is in the dotted line position as the signal 1 is in the danger position, thence by wires 174 and 143 to the negative terminal of the battery 106. The result of the flow of current last described is to energize control relay 72 thereby causing armature 175 to be raised to the upper position as shown, consequently, allowing current to flow from the positive terminal of the battery 119 by wires 176, 177 and 178 and armature 175 to wire 179 and by one of the multiple paths from wire 179 to wire 180 to and through the signal mechanism of signal 8, and by means of wires 181, 182 and 183, to the negative terminal of the battery 119. The current flowing in the last traced path causes the signal arm 8 to move to the caution position, but it will not be moved to the proceed position because current cannot flow from wire 179 through wire 184 and through armature 104 to wire 185 and thence to the signal mechanism, because the path for current which was formed by the raising of armature 150 allowed current to flow from battery 106 through pole changing switch 1¹ in such a direction that control relay 72 was so energized that it caused armature 104 to break contact with wire 185. Thus it will be seen by placing the left hand end of Fig. 1 in a position which makes it a continuation of the right hand end of Fig. 4, that a train moving in an easterly direction upon the track circuit section C² would have a danger aspect exhibited by signal 1 behind it and a caution aspect exhibited by signal 8 behind it one block in the rear, and that such condition would continue to exist just so long as any part of the train occupied the rails forming part of track circuit section C², and also just so long as a train occupied the rails of track circuit section C³, because the entrance to and presence of a train upon the track circuit section C³ would cause a deenergization of track relay 24 thereby allowing armature 186 to move to the lower position breaking contact with wire 187, so that although the passage of the train entirely off from the rails of track circuit section C² would allow relay 23 to be energized and cause armature 183 to be raised thereby completing the break that was made in the circuit for control relay 58,

nevertheless the circuit for control relay 58 would be broken between armature 186 and wire 187 so that armature 184 would continue in its lower position maintaining the energization of stick relay 74 and causing armature 150 to remain in the upper position making contact with wire 170.

As soon as the train which I have assumed to be moving easterly upon the track-way has passed upon the section A¹, control relay 58 will be energized by a current which flows from battery 108 through the armatures 188 and 189 in their lower position because they will be in their lower position for reasons to be later explained. The circuit in which current flows, including control relay 58, will therefore be as follows: positive terminal of battery 108, wires 190 and 191, armature 188, wires 192, 193, 194, 195, 196, 225, 154 and 197, control relay 58, wire 198, armature 133, wire 199, armature 186, wires 187 and 200, armature 189 and wires 201 and 202 to the negative terminal of the battery 108. The flow of current in the path last described causes armature 184 to be raised, thereby breaking the circuit for maintaining the energization of stick relay 74 and allowing its armatures to fall and also allowing current to flow from the positive terminal of battery 106 through wires 141, 145 and 146 and armature 184 to wire 203 and thence by the caution control wire 204 to the signal 1, returning by wires 205, 142 and 143 to the negative terminal of the battery 106. Current would not flow, however, from wire 203 to wire 206 and through armature 90 to proceed control wire 207 to the signal 1, because the flow of current from the battery 108 through the coil of control relay 58 causes such an energization of the poles of control relay 58 that the armature 90 is moved to the left away from contact with wire 207, consequently, the train standing upon track circuit section A¹ would be protected by a signal 2 at danger directly behind it for reasons to be later explained and by a caution signal 1, one block in the rear.

The energization of control relay 58 in the manner heretofore explained and the movement of the signal 1 to the caution position causes armature 208 to be moved to the upper position and also causes pole changing switch 1¹ to be thrown from the dotted line position to the full line position, so that the current which flowed as hereinbefore explained from the positive terminal of battery 106 by means of wires 141, 145 and 151 and pole changing switch arm 152 to wire 153 and thence by wires 154, 155, 156, 157, 158, 159 and 160 to control relay 72 would now flow from the positive terminal of battery 106 to wires 141, 145, and 151 to pole changing switch arm 152, thence by wires 171 and 209 to armature 208 and then

by means of wires 210 and 168 to armature 167 and then by wire 166 to armature 165, through wires 164 and 163 to armature 162 and then by means of wire 161, to control 5 relay 72. It will thus be seen that the polarity of the current then flowing through the control relay 72 would be exactly the opposite to that which flowed when the pole changing switch 1¹ was in the dotted line 10 position and the armature 150 was in the raised position, and as the current which formerly flowed caused armature 104 to be moved to the left, the current which now flows will cause armature 104 to be moved 15 to the right making contact with wire 185. The current which now flows and which has heretofore been traced as flowing through control relay 72 by means of wire 161, would flow back to the negative terminal of the 20 battery 106 in the following path: wires 160, 159, 158, 157, 156, 155, 154 and 153 to pole changing switch arm 173, thence by wires 174 and 143 to the negative terminal of the 25 battery.

25 The movement of polarized armature 104 to the right while armature 175 is in the raised position, would allow current to flow from battery 119 to the proceed control wire and flow as follows: positive terminal of the battery 119, wires 176, 177 and 178, armature 175, wires 179 and 184, polarized armature 104, and proceed control wire 185 to the signal 8 thence returning by wires 181, 182 and 183 to the negative terminal of 30 the battery 119, thus causing the signal 8 to be moved to the full proceed position, so that then the train standing on track section A¹ would have a full danger signal protecting it directly back of it, a caution signal 1, one block in the rear, and a full proceed signal 8 two blocks in the rear.

35 Ignoring for a moment the effect of the train upon track section A¹, I will return to the effect of the train when it enters track 40 circuit section C¹ upon signal 15.

When the train which has been considered, entered upon track circuit section C¹, it would also place the signal 15 in the full danger position if it were not already in 45 that position, because the entrance of a train upon track circuit section C¹ would deenergize relay 22 which, as hereinbefore explained, would deenergize control relay 57, if it were not already deenergized, thereby 50 allowing armature 220 to drop which would cause a deenergization of control relay 59, because relay 59 has current flowing through it when energized in a circuit as follows: positive terminal of battery 105, wires 124, 55 125 and 221, arm 222 of pole changing switch 16¹; in the dotted line position, if signal 16 is in the danger position and wires 224, 155, 154, 225 and 226 to control relay 59, then by wire 213, armature 212, wire 60 348, armature 219, wire 227, armature 228,

wires 229, and 230, armature 220, wires 231, 232, and 265, arm 223 of pole changing switch 16¹, and thence by wires 233 and 132 to the negative terminal of battery 105. The circuit above traced as heretofore 70 pointed out would be broken by the dropping of armature 220 upon the entrance of a train to track section C¹, if it were not already broken because of the fact that the armature 220 was then already in the lower 75 position, and the armature 220 would remain in the lower position just so long as the train was upon track circuit section C¹ because of the continued deenergization of track relay 22 and the consequent deener- 80 gization of control relay 57.

When the train considered moved from track circuit section C¹ to track circuit section C², it would allow track relay 22 to be again energized, but it would at the same 85 time, however, deenergize relay 23 and subsequently relay 24 upon entering track circuit section C³, and so cause armature 219 and subsequently armature 212 to drop to the lower position, thereby breaking the 90 circuit of control relay 59 which is connected to armature 212 by means of wire 213, so that armature 214 of control relay 59 would remain in the lower position to which it had been allowed to move, if it 95 were not already in that position, by the deenergization of control relay 57, thereby continuing the disconnection of wire 215, which feeds current to both proceed control wire and the caution control wire of signal 15, from its previously formed connection by means of wires 216, 217 and 218, with the positive terminal of the battery 107, thus causing the signal 15 to remain in the full biased or danger position, if it is already 100 there, or allow it to move to such position, if it is not already there.

I will now return to consideration of the operation which takes place upon the entrance of the train to track circuit section 110 A¹.

Upon the entrance of a train onto track circuit section A¹, the relay 25 is deenergized, thereby allowing armature 234 to drop, thus breaking connection between armature 234 and wire 235, so that control relay 60 is deenergized. The normal circuit for control relay 60, in which current flows, is as follows: positive terminal of the battery 109, wires 236, 237 and 238, arm 239 of pole changing switch 3¹ in the full line position, wires 240, 241, 242 and 243, armature 244, wires 245 and 235, armature 234, wires 246 and 247, control relay 60, wires 248, 249, 194, 250, 251, 252, 253 and 254, arm 255 of pole changing switch 3¹, and wires 256 and 257 to the negative terminal of battery 109. The breaking of the above traced path causes a cessation of the flow of current through the control relay 60, thus 120 125 130

allowing the armature 258 to drop to the lower position, so that the current which previously flowed from battery 108 by means of wires 190 and 259, through armature 258 to wire 260, and thence to both the proceed control wire and the caution control wire of signal 2, is interrupted, and signal 2 moves to the full danger or bias position.

The movement of signal 2, to the danger position causes circuit controller arm 41 to break contact with wire 261, consequently relay 85, which I will designate as a pole changing relay becomes deenergized, because the circuit controller arm 41 is an integral part of the circuit controlling pole changing relay 85 and normally current flows to energize the pole changing relay 85 in the following circuit: positive terminal of battery 109, wires 236, 237 and 238, 20 arm 239, of pole changing switch 3¹ in the full line position, wires 240, 241, 242 and 262, armature 263, wires 264, 334, and 261, metallic arc 333, arm 41, then by wire 266 to pole changing relay 85, and thence by 25 wires 267, 249, 194, 250, 251, 252, 253 and 254 to arm 255 of pole changing switch 3¹, and thence by wires 256 and 257 to the negative terminal of the battery 109.

It is to be noted that battery 109 furnishes energy for both control relay 60 and pole changing relay 85, and that between the batteries and the relays a pole changing switch is interposed, but the pole changing switch and the polarity of the current flow 35 has no effect upon pole changing relay 85 because a current flowing through pole changing relay 85 in either direction causes it to hold the neutral armatures 188 and 189 in the upper position and if the current 40 ceases the armatures fall to the lower position. The polarity of the current flowing through the control relay 60, however, determines the aspect of signal 2 because the normal flow of current from battery 109 to 45 control relay 60 is in such a direction that armature 92 is moved to the right into contact with the proceed control wire 268, but when the current from the battery 109 through the control relay 60 is in the reverse 50 direction the polarized armature 92 is moved to the left out of contact with proceed control wire 268, thereby causing the arm 2 to move to the caution position from the proceed position, if armature 258 is at that time 55 in the upper position but if the current ceases entirely as by the presence of a train upon track circuit section A¹, causing a deenergization of relay 25, and allowing armature 234 to fall, then current from battery 108 could 60 also be cut off from caution control wire 269 and the signal 2 will move to the full danger or bias position.

The train upon track circuit section A¹ would then be protected by a full danger 65 signal 2 directly behind it, and a caution sig-

nal 1, one block in the rear, and as control relay 58 would be energized by the passage of the train off from track circuit section C⁸, the circuit heretofore traced for control relay 72, would be completed through the pole 70 changing switch 1¹ in the full line position, so that current would flow through the battery 106, through the control relay 72 in the normal direction, so that polarized armature 104 would be moved to the right thereby 75 completing the circuit from battery 119 to both the caution control wire 180 and the proceed control wire 185 of signal 8, so that there would also be a proceed signal two blocks in the rear of the train. 80

The train which has hereinbefore been assumed to be upon the trackway illustrated by the drawings, is now positioned on the track circuit section A¹ directly in the rear of the insulating joints opposite signal 3. 85 It will be assumed that no train is upon any part of the single track block D and that, therefore, signals 3, 4, 5, 6, 11, 12, are all in the normal position as shown, so that the train by reason of the proceed position of signal 3 has full rights to enter the single track block D at full speed. 90

The progress of the train through the single track block D will now be described; having reference merely to those signals upon 95 which it depends for its rights to advance; to-wit, signals 3, 4, 5 and 6.

Upon the entrance of the first pair of wheels of the first truck of the train upon the track circuit section D¹, the track relay 100 26 is deenergized thus allowing armature 270 to fall and as the circuit for control relay 62 is formed through armature 270, in its upper position through wire 288, then control relay 62 will be deenergized and allow armature 271 to fall to its lower position, thus interrupting the flow of current from battery 109, through wires 236, 237 and 314, and armature 271 to wire 315 and thence to caution control wire 273 and proceed control 110 wire 272 of signal 3. Signal 3 consequently moves to the full biased or danger position protecting the rear of the train.

The deenergization of relay 26 also allows armature 316 to fall, and as hereinbefore explained, as it moves quicker than the arm of the signal 3, it will close a contact connected with wire 317 before conducting circuit controller arm 43 has moved out of contact with metallic arc 318, so that a circuit will be 115 formed through the stick relay 76, in which current flows, as follows: positive terminal of battery 109, wires 236 and 319, conducting controller arm 43, metallic arc 318, wire 317, armature 316, wires 320 and 321, stick relay 120 76 and wires 322, 323, and 257 to the negative terminal of the battery 109. The result of current flow in the above traced path will be the preliminary energization of stick relay 76, and consequently, the raising of ar- 125 130

matures 324, 325 and 326. The raising of armature 324 while armature 271 is in its lower position causes current to flow in a maintaining circuit as follows: positive terminal of battery 109, wires 236, 237, and 314, armature 271, wire 327, armature 324, wires 328 and 321, stick relay 76 and wires 322, 323 and 257 to the negative terminal of the battery 109. The current flowing in the above traced path will maintain the stick relay 76 energized, even after conducting circuit controller arm 43 moves out of contact with metallic arc 318, due to the movement of the signal mechanism and signal to the full biased or danger position, during all of the time that the train is upon track circuit section D¹ and also while the train is upon track circuit section D², because the entrance of the train to track circuit section D², causes a deenergization of relay 27, thus allowing armature 274 to fall, and breaking the circuit for control relay 62, which is connected to armature 274, through wire 288, armature 270, and wire 289.

25 The object of energizing stick relay 76 is to close a circuit through control relay 60, so that signal 2 may receive current from battery 108 through its caution control wire, so as to be thereby moved to the caution position. While the train was upon track circuit section A¹, relay 25 was deenergized allowing armature 234 to fall, thus breaking the circuit through control relay 60, which is connected to armature 234, by means of wires 247 and 246. When the train moved off from track circuit section A¹ and entirely upon track circuit section D¹, relay 25 was again energized and armature 234 was raised, but at the same time armature 244 controlled by relay 26, was allowed to fall to the lower position, thus breaking the same circuit at another point as the circuit for control relay 60 is controlled through armature 244 by means of wires 245 and 235, armature 234, wires 246 and 247. When stick relay 76 is energized and armature 326 is raised, current can then flow through the control relay 60 from battery 109 in the following circuit: positive terminal of battery 109, wires 236, 237 and 238, arm 239 of pole changing switch 3¹, which is in the dotted line position, because signal 3 is in the danger position, wires 254, 253, 252, 251, 250, 194, 249 and 248, to control relay 60, from control relay 60, through wires 247 and 246, armature 234, wires 235 and 329, armature 326, wires 330, 240 and 331, arm 255 of pole changing switch 3¹ and wires 256 and 257 to the negative terminal of the battery 109. 60 Current flowing in the above traced path energizes control relay 60, causing armature 258 to be moved to the upper position, but, as pole changing switch 3¹ has been reversed, the direction of current flowing from battery 109 through control relay 60, is the reverse

of normal, consequently, the armature 92 is moved to the left out of contact with proceed control wire 268. The raising of armature 258 allows current to flow from battery 108 to signal 2, in the following path: positive terminal of battery 108, wires 190 and 259, armature 258, wires 260 and 269, signal mechanism 2, and wires 332 and 202 to the negative terminal of the battery 108. The current flowing in the above traced path causes the signal 2 to assume the caution aspect. 70

The presence of the train upon track circuit section A¹, caused the signal 2 to assume the danger aspect, thus interrupting the circuit at conducting controller arm 41 between wires 261 and 266, thus causing pole changer relay 85 to become deenergized as the circuit for pole changer relay 85 is formed through the circuit controller arm 41, by means of wire 266. The passage of the train entirely onto track circuit section D¹ cause as has hereinbefore pointed out, a movement of signal 2 to the caution position, thus allowing conducting controller arm 41 to again make contact with metallic strip 333, and thus complete the circuit from wire 261 to wire 266, but the movement of the same into the track circuit section D¹, deenergized control relay 62 and caused armature 263 to fall so that the circuit of pole changer relay 85 is broken at another point. The energization of stick relay 76, however, forms a circuit in which current can flow to the pole changing relay 85 as follows: positive terminal of battery 109, wires 236, 237 and 238, arm 239 in the dotted line position, wires 254, 253, 252, 251, 250, 194, 249 and 267 to pole changing relay 85 and from the pole changing relay by wire 266, conducting controller arm 41, metallic arc 333, wires 261, 334, 335 and 336, armature 325, wires 337, 241, 240 and 331, controller arm 255 of pole changing switch 3¹, in the dotted line position, and wires 256 and 257 to the negative terminal of the battery 109. 90 95 100 105 110

The energization of pole changing relay 85 in the manner just described causes the armatures 188 and 189 to be raised, thereby restoring all parts of the mechanism connected with single track section C to the normal position as shown. 115

The progress of the train through track circuit section D² does not alter any of the conditions which have heretofore been established, but upon the entrance of the train onto track circuit section D³, the track relay 28 is deenergized and armature 275 is allowed to fall, thus deenergizing control relay 64 which allows armature 276 to fall, thus allowing signal 4 to assume the full biased or danger position as operating current from battery 111 is thereby cut off from both the caution control wire 338 and the proceed control wire 339 of signal 4. 120 125 130

The entrance of the train to track circuit section D³ in a manner identical to that described in connection with signal 3, causes a preliminary and maintained energization 5 of stick relay 78, so that control relay 62 which was deenergized by reason of the armature 274 being in its lower position, would still be deenergized by reason of armature 308 being in its lower position as the normal 10 circuit for control relay 62 is as follows: positive terminal of battery 111, wires 278, 279 and 280, arm 281 of pole changing switch 4¹ in the full line position, wires 297, 296 and 302, armature 303, wires 304 and 15 292, armature 291, wire 290, armature 274, wire 289, armature 270, wire 288, control relay 62, wires 287, 253, 286, 285, 284, 283 and 282, arm 299 of pole changing switch 4¹ in the full line position, and wires 300 and 301 20 to the negative terminal of the battery 111, but although armature 303 is in its lower position a circuit will be formed through control relay 62 in which current flows as follows: positive terminal of battery 111, 25 wires 278, 279 and 280, arm 281 in the dotted line position due to the position of the pole changing switch 4¹ by the movement of the signal 4 to the danger position, wires 282, 283, 284, 285, 286, 253 and 287, control relay 30 30 62, wire 288, armature 270, wire 289, armature 274, wire 290, armature 291, wires 292 and 293, armature 294, wires 295, 296, 297 and 298, arm 299, in the dotted line position and wires 300 and 301 to the negative 35 terminal of the battery 111. The current flowing in the above traced path would energize the control relay 62, but as the current flows in a direction opposite to the normal flow, polarized armature 94 would be moved to 40 the left, thereby breaking contact with the proceed control wire 272 of signal 3, but as armature 271 would be thereby raised, current would flow in a path heretofore traced from battery 109, through the caution control 45 wire 273, to signal 3, returning in the usual manner so that the signal 3 would assume the caution aspect. The train upon track section D³ would thus be protected by a full danger signal directly behind it and 50 a caution signal one block in the rear, which condition would be also maintained during its passage onto and through section D⁴ because its presence upon track circuit section D⁴ would cause a deenergization of track relay 29 and thus allow armature 305 to fall, which would act in the same manner as armature 275 to break the circuit of control 55 relay 64.

When the train passed from the section D², to track circuit section D³, control relay 62 became energized, therefore armatures 263 and 271 were raised thus breaking the circuit for stick relay 76 and so causing armatures 324, 325 and 326 to fall, and also 60 causing signal 3 to move to the caution position.

sition, thus shifting pole changer switch 3¹ from the dotted line position to the full line position, so that current then flowed from battery 109 to control relay 60 in the normal direction as follows: positive terminal 70 of battery 109, wires 236, 237 and 238, arm 239 of pole changing switch 3¹ in the full line position, wires 240, 241, 242 and 243, armature 244, wires 245 and 235, armature 234, wires 246 and 247, control relay 60, 75 wires 248, 249, 194, 250, 251, 252, 253 and 254, arm 255 of pole changing switch 3¹, in the full line position and wires 256 and 257 to the negative terminal of the battery 109. As the current then flows through the control 80 relay 60 in the normal direction, the polarized armature 92 will be moved to the right thereby making contact with proceed control wire 268 so that current may flow from battery 108 in the path heretofore traced to and through the proceed control wire 268 and the signal 2, returning in the usual path. The train while situated upon either track circuit section D³ or D⁴ will therefore have a full danger signal 4 directly 85 behind it, a caution signal 3 one block in the rear, and a proceed signal 2, two blocks in the rear.

When the train moves upon track circuit section D⁴, track relay 30 is deenergized and 90 armature 306 is allowed to fall thereby breaking the circuit for control relay 66, and allowing armatures 311 and 307 to fall, so that in the same manner as heretofore described in connection with signals 3 and 4, the signal 95 5 will move to the full biased or danger position and stick relay 80 will be energized and maintained energized, so that the operation will be identical with that which took place when the train passed from track circuit section D² to track circuit section D³ that is, the circuit for control relay 64, which normally passes through armature 311, will be broken at that point, but another circuit in 100 which current flows in a direction reverse to 110 normal will be formed from battery 113 through the pole changing switch 5¹ in the dotted line position due to the danger position of signal 5 and through armature 309 in the raised position. This current will 115 act upon control relay 64 just as the current which has hereinbefore been described flowing from battery 111 acted upon control relay 62, so that polarized armature 96 will be moved to the left breaking contact with 120 the proceed control wire 339 and armature 276 will be moved to the upper position allowing current to flow from battery 111 to and through the caution control wire 338, to cause the signal 4 to assume the caution 125 aspect. At the same time stick relay 78 will become deenergized by reason of the raising of armature 276, and the current flowing from battery 111 to control relay 62, would flow in its normal path through 130

armature 303, controlled by control relay 64, and as signal 4 would be moved to the caution position pole changing switch 4¹ would be moved to the full line position so that the current flowing in its normal direction from battery 111, would flow in the following path: positive terminal of battery 111, wires 278, 279 and 280, arm 281 of pole changing switch 4¹, in the full line position, wires 297, 296 and 302, armature 303, wires 304 and 292, armature 291, wire 290, armature 274, wire 289, armature 270, wire 288, control relay 62, wires 287, 253, 286, 285, 284, 283 and 282, arm 299 of pole changing switch 4¹ in the full line position and wires 300 and 301 to the negative terminal of battery 111. As the current flows from battery 111 to control relay 62 in the normal direction the armature 94 will be moved to the right making contact with proceed control wire 272 of signal 3, consequently, signal 3 will be moved to the proceed position.

During the time that the train is upon track circuit section D⁵, the conditions will be maintained as already described. The movement of the train upon track circuit section D⁶ will not alter any of the essential conditions, the only change being that the circuit of control relay 66 instead of being broken at armature 306 will be broken at armature 310, which will be allowed to fall by the deenergization of track relay 31.

The movement of the train onto track circuit section B¹, would have exactly the same effect that the movement of the train upon the track circuit section A¹ had, as hereinbefore described, that is, control relay 68, would be deenergized, thus allowing armature 340 to fall, thereby interrupting both the caution and proceed control wires governing signal 6, which, consequently, moves to the full biased or danger position, and by so doing, causes conducting controller arm 51 to move from in contact with metallic strip 341, thus breaking the circuit of pole changing relay 87, and allowing armatures 342 and 343 to move to the lower position, and as armatures 306 and 310 would be in the upper position after the train leaves section D⁶, a current would flow from battery 115 to control relay 66, in a direction reverse to normal so that polarized armature 98 would be moved to the left breaking contact with proceed control wire 344 and armature 307 would be raised making contact with caution control wire 345, so that signal 5 would be moved to the caution position, just as has been described hereinbefore in connection with signal 1.

The energization of control relay 66 would cause a deenergization of stick relay 80, consequently, armature 309 would be allowed to fall and the current from battery 113 would flow in its normal direction through armature 311 to control relay 64, thereby

causing polarized armature 96 to be moved to the right making contact with proceed control wire 339 of signal 4, thus causing signal 4 to move to proceed position so that the train upon section B¹ would have exhibited behind it a full danger signal 6 directly in the rear, a caution signal 5 one block in the rear, and a proceed signal 4, two blocks in the rear.

The condition of the signals and the circuits would remain as already described upon the movement of the train onto track circuit section B² except that the circuit for control relay 68 would be broken at armature 346 by the deenergization of track relay 33 instead of by the armature 347.

The further movement of the train on the system would merely result in a repetition of those operations which have already been described in connection with signals 1, 2, 3 and 4, and therefore does not need further description.

The circuits and controlling apparatus and signals governing the movements of a train for one direction only having been described in connection with single track block D, it now remains to describe the means for obtaining "head-on" protection, that is, the means for preventing a train from entering the single track block D while the train which has hereinbefore been considered, is progressing through the single track block D.

As soon as the train which has hereinbefore been considered, entered upon track circuit section D¹ from track circuit section A¹, it was necessary that signals such as 11, 12, 13 and 14, governing train movements in a westerly direction over single track block D, should be placed in a danger position. The entrance of a train from track circuit section A¹ to track circuit section D¹ deenergized track relay 26, which allowed armature 350 to fall to the lower position, thereby breaking the circuit of control relay 63 of signal 13, this circuit being identical in all respects with the circuit of the control relay of signal 1. The deenergization of control relay 63 allows armature 351 to fall, thereby interrupting the current from battery 110 to the caution control wire 352 and the proceed control wire 353, of signal 13, consequently the signal moves to the full biased or danger position. At the same time the falling of armature 354 by reason of the deenergization of control relay 63, breaks the circuit through control relay 65, the circuit of which is identical with that of signal 8, hereinbefore described. The deenergization of control relay 65 allows armature 355 to fall thereby causing an interruption of the current from battery 112 to the caution control wire 356 and the proceed control wire 357 of signal 12 so that signal 12 will move to the danger posi-

tion. The falling of armature 358, allowed by the deenergization of control relay 65, interrupts the circuit for control relay 67, the circuit of which is identical with that of the control relay of signal 3, hereinbefore described. The deenergization of control relay 67 allows armature 359 to fall, thereby interrupting the flow of current from battery 114 to the caution control wire 360, and the proceed control wire 361 of signal 11, thus allowing the signal 11 to assume the full danger or biased position.

It is thus seen that the entrance of a train moving in an easterly direction onto the track circuit section D¹ will instantly cause all of the signals governing movements in a westerly direction over the single track block D, to move to the full biased or danger position so that the east bound train is fully protected from any opposing train movement.

While the east bound train is upon the track circuit section D¹, the condition of signals 11 to 13 inclusive would remain as described and due to the reasons given. When the train is upon track circuit section D², the circuit for control relay 63 is broken at armature 362, so that the signals 11, 12 and 13 remain in the danger position.

When the train enters upon the section D³, the circuit for control relay 65 would be broken at armature 363 and also at armature 364, due to the energization of stick relay 78, this latter break in the circuit being made simply as an additional precaution to insure the deenergization of control relay 65. When the train moves upon track circuit section D⁴, the circuit for control relay 65 would be broken at armature 365

and at armature 364. When the train moves upon track circuit section D⁵, the circuit for control relay 67 would be broken at armature 366, and at armature 367, of stick relay 80. When the train enters upon track circuit section D⁶, the circuit for control relay 67 would be broken at armature 368 and armature 367.

The movement of the train from track circuit section D⁶ to track circuit section B¹ would result in signals 11, 12 and 13 all being left in the full clear position, because when the train which has hereinbefore been considered passed signal 18, and was entirely upon track circuit section D³, the control relay 63 of signal 13 immediately became energized as there was no train upon section D², so armature 362 was moved to the upper position and as there was no train upon track circuit section D¹, the armature 350 was raised to the upper position so that a circuit from battery 369 was formed to control relay 63, identical with a circuit heretofore described controlling control relay 58 of signal 1, so that signal 13 would assume the full clear position.

The passage of the train from track circuit section D⁴ to D⁵ would allow track relay 29 to become energized, thereby raising armature 365 to the upper position and at the same time track relay 28 would be energized thereby raising armature 363 to the upper position, and at the same time armature 364 would be in the lower position due to the passage of the train off from track circuit section D⁴, resulting in a deenergization of stick relay 78, and at the same time as hereinbefore explained control relay 63 would be energized thereby causing armature 354 to be in the upper position, consequently, current from battery 110 would flow through and energize control relay 65 by a circuit identical with that hereinbefore described in connection with the control relay 64. The movement of the train from track circuit section D⁶ to track circuit section B¹ would allow relay 31 to become energized thereby raising armature 368 to the upper position and at the same time armature 366 would be in its upper position due to a previous energization of track relay 30 and armature 367 would be in the lower position due to the deenergization of stick relay 80, by the movement of the train from track circuit section D⁶ to track circuit section B¹, and armature 358 controlled by control relay 65 would be in the upper position due to the energization of control relay 65 in a manner hereinbefore described so that current would flow from battery 112 to energize control relay 67 and so place signal 11 in a proceed position by a circuit identical with that by which current normally flows from battery 111 to energize control relay 62, controlling signal 3.

The operation of the signal mechanism and controlling arrangements for signals governing following movements, and also for signals governing opposing movements has now been described with the exception that the action of signals such as 2, 14, 6 and 10, for opposing movements remains to be described.

The control relay for signal 10, 's 69, and the circuit including the control relay 69 in which current normally flows is as follows: positive terminal of battery 114, wires 369, 370 and 371, arm 372 of pole changing switch 11¹ in the full line position, wires 373, 374, 375, 376 and 427, armature 377, wires 378 and 379, armature 380, wires 381 and 382, 120 armature 383, wire 384, control relay 69, wires 385, 386, 387, 388, 389, 390 and 391, arm 392, of pole changing switch 11¹, in the full line position, and wires 393 and 394 to the negative terminal of the battery 114. 125 The current flowing in the above traced path with the parts as shown in the drawing will be in such a direction through the control relay 69, that armature 101 will be moved toward the right into contact with proceed 130

control wire 395, and consequently, the signal 10 will be held in the proceed position, but, as soon as a train moving in an easterly direction, enters the track circuit section 5 D¹, then the signal 11 is allowed to fall to the danger position, thereby moving the pole changing switch 11¹ from the full line position to the dotted line position, so that current which normally flows from the positive 10 terminal of battery 114, by means of wires 369, 370 and 371, and arm 372 of pole changing switch 11¹ in the full line position, to wire 373, and thence through the wires and armature heretofore pointed out to wire 384, 15 would instead flow from the positive terminal of the battery 114, through wires 369, 370, and 371, arm 372 of pole changing switch 11¹ in the dotted line position, and thence by means of wire 391, 390, 389, 388, 20 387, 386 and 385, to the other side of the control relay 69, so that the current through the control relay 69 would be reversed in direction and the polarized armature 101 would be moved to the left breaking contact 25 with proceed control wire 395 of signal 10 so that the signal would immediately assume the caution aspect, the moment a train entered from section A¹ onto section D¹. The signal 10 would remain in the caution position during the progress of the east bound train through the single track block D until such train entered upon the rails of track circuit section D⁶, whereupon by the deenergization of track relay 31 and the consequent 30 dropping of armature 377 the circuit for the control relay 69 would be broken and the armature 396 would be allowed to fall to its lower position, thereby interrupting the flow of current from the battery 116 to the caution control wire 397 of signal 10 and causing 35 said signal to go to the stop position. The movement of the train from track circuit section D⁶ upon to track circuit section B¹, would break the same circuit at armature 380 controlled by track relay 32, and the movement of the train onto track circuit section B² would break the same circuit at armature 383 controlled by track relay 33. 40

At the same time that signal 10 moves to 50 the caution position, signal 9 also moves to the caution position, because the entrance of a train into track circuit section D¹ from A¹ will deenergize control relays 63, 65 and 67 as hereinbefore pointed out and will cause 55 signal 11 to move to the danger position thereby causing conducting controller arm 49 to move out of contact with metallic arc 398 and will allow armature 399 to fall to its lower position, consequently, the circuit 60 through pole changing relay 88 will be broken at armature 399. This circuit is normally as follows: positive terminal of battery 114, wires 369, 370 and 371, arm 372 of pole changing switch 11¹, in the full line position, wires 373, 374, 375, 376 and 400, armature 399, wires 401, 402, 403 and 404, metallic arc 405, conducting circuit controller arm 52, wire 406, pole changing relay 88, wires 407, 386, 387, 388, 389, 390 and 391, arm 392 of pole changing relay 11¹ in the 70 full line position, and wires 393 and 394 to the negative terminal of the battery 114. As soon as the train moves from track circuit section A¹ to track circuit section D¹, the circuit heretofore traced through pole changing relay 88 would be broken at armature 399, and, consequently, armatures 408 and 409 would be allowed to fall to their lower position thus reversing the flow of current from battery 116 to control relay 71, so that polarized armature 103 would be moved out of contact with proceed control wire 410 of signal 9, thereby interrupting the flow of current from battery 118 to the proceed control wire of signal 9, thus allowing the signal to 80 assume the caution aspect.

Signal 9 would remain in the caution position upon the passage of the train from track circuit section D⁶ onto track circuit section B¹, by reason of the fact that signal 90 10 having moved to the danger position when the train moved upon track circuit section D⁶, thereby opening the circuit of pole changing relay 88 at the conducting circuit controller arm 52 and would also be 95 maintained in such position after the train passed upon track circuit section B² for the same reason.

It will be noted that signals 3, 7, 11 and 15 have two conducting circuit controller arms 100 operated therewith, and that one of the conducting circuit controller arms associated with each of the said signals, to-wit, 44, 54, 49, and 39, are in a multiple circuit with the upper armatures of control relays 62, 70, 67 105 and 59 respectively. The result obtained by the use of the multiple connection shown can be best made clear by an example. The movement of a train from track circuit section B² upon to single track block E if we 110 consider single track block C a continuation of single track block E, would cause control relay 59 to become deenergized, and allow armature 411 to fall to the lower position. At the same time the deenergization of relay 59 will open armature 214, put signal 15 to danger and open circuit controller 39. Thus the multiple branches through armature 411 and circuit controller 39 will both 115 be broken, thereby breaking a circuit through pole changing relay 86 identical with that which includes pole changing relay 88 hereinbefore described, thus causing armatures 412 and 413 to drop and reverse the polarity of current flowing through control relay 63, which is included in a circuit in which current normally flows as follows: 120 positive terminal of battery 369, wires 414 and 415, armature 412, wires 416 and 417, armature 350, wire 418, armature 362, wire 125 400, armature 399, wires 401, 402, 403 and 404, metallic arc 405, conducting circuit controller arm 52, wire 406, pole changing relay 88, wires 407, 386, 387, 388, 389, 390 and 391, arm 392 of pole changing relay 11¹ in the full line position, and wires 393 and 394 to the negative terminal of the battery 114. As soon as the train moves from track circuit section A¹ to track circuit section D¹, the circuit heretofore traced through pole changing relay 88 would be broken at armature 399, and, consequently, armatures 408 and 409 would be allowed to fall to their lower position thus reversing the flow of current from battery 116 to control relay 71, so that polarized armature 103 would be moved out of contact with proceed control wire 410 of signal 9, thereby interrupting the flow of current from battery 118 to the proceed control wire of signal 9, thus allowing the signal to 80 assume the caution aspect.

Signal 9 would remain in the caution position upon the passage of the train from track circuit section D⁶ onto track circuit section B¹, by reason of the fact that signal 90 10 having moved to the danger position when the train moved upon track circuit section D⁶, thereby opening the circuit of pole changing relay 88 at the conducting circuit controller arm 52 and would also be 95 maintained in such position after the train passed upon track circuit section B² for the same reason.

It will be noted that signals 3, 7, 11 and 15 have two conducting circuit controller arms 100 operated therewith, and that one of the conducting circuit controller arms associated with each of the said signals, to-wit, 44, 54, 49, and 39, are in a multiple circuit with the upper armatures of control relays 62, 70, 67 105 and 59 respectively. The result obtained by the use of the multiple connection shown can be best made clear by an example. The movement of a train from track circuit section B² upon to single track block E if we 110 consider single track block C a continuation of single track block E, would cause control relay 59 to become deenergized, and allow armature 411 to fall to the lower position. At the same time the deenergization of relay 59 will open armature 214, put signal 15 to danger and open circuit controller 39. Thus the multiple branches through armature 411 and circuit controller 39 will both 115 be broken, thereby breaking a circuit through pole changing relay 86 identical with that which includes pole changing relay 88 hereinbefore described, thus causing armatures 412 and 413 to drop and reverse the polarity of current flowing through control relay 63, which is included in a circuit in which current normally flows as follows: 120 positive terminal of battery 369, wires 414 and 415, armature 412, wires 416 and 417, armature 350, wire 418, armature 362, wire 125 400, armature 399, wires 401, 402, 403 and 404, metallic arc 405, conducting circuit controller arm 52, wire 406, pole changing relay 88, wires 407, 386, 387, 388, 389, 390 and 391, arm 392 of pole changing relay 11¹ in the full line position, and wires 393 and 394 to the negative terminal of the battery 114. As soon as the train moves from track circuit section A¹ to track circuit section D¹, the circuit heretofore traced through pole changing relay 88 would be broken at armature 399, and, consequently, armatures 408 and 409 would be allowed to fall to their lower position thus reversing the flow of current from battery 116 to control relay 71, so that polarized armature 103 would be moved out of contact with proceed control wire 410 of signal 9, thereby interrupting the flow of current from battery 118 to the proceed control wire of signal 9, thus allowing the signal to 80 assume the caution aspect.

419, control relay 63, wires 420, 286, 253, 252, 421, 422 and 423, armature 413, and wires 424 and 425 to the negative terminal of the battery 369. The reversal of current 5 through control relay 63, is preceded by a cessation of current due to the fact that an appreciable length of time intervenes between the time when armatures 412 and 413 are making contact on their front contacts 10 and the time when they make contact with their back contacts; furthermore, a certain time is consumed in reversing the polarity of the core of control relay 63 so that armature 354 drops and remains out of contact 15 with wire 426 for an appreciable length of time, consequently, the circuit for control relay 65 is broken for an appreciable length of time so that armature 358 drops and remains dropped for an appreciable length of 20 time, causing control relay 67 to become de-energized, allowing its armature 399 to drop and armature 399 dropping would, if conducting circuit controller arm 49 were not used, break the circuit heretofore traced for 25 pole changing relay 88 so that the same operations would take place with control relay 71, that took place with control relays 63, 65 and 67, but, by using circuit controller arm 49, a shunt is formed around relay 30 armature 399, controlled by control relay 67, so that the current which normally flows from battery 114 through pole changing relay 88 by means of wires 369, 370 and 371, arm 372 of pole changing switch 11¹, in the 35 full line position, wires 373, 374, 375, 376 and 400, armature 399, and wire 401 to wire 402, and thence to pole changing relay 88 could flow by the multiple path from wire 400 through wire 428, metallic arc 398, conducting controller arm 49, and wire 429 to 40 wire 402 and thence to pole changing relay 88. It is true that the same momentary de-energization of the control relay 67 which permits the armature 399 to drop momenta- 45 rily will also drop the armature 359 momenta- rily and permit the signal 11 to start to drop from its clear to its danger position. The controller arm 49 moves with the signal 11 but this movement, on account of the 50 inertia of the signal 11, does not proceed far enough to break contact at 49 during the short momentary de-energization of the control relay 67 so that the circuit through the relay 88 is not interrupted. By employing 55 the circuit controller arm similar to 49, on the signals as shown, a train entering upon one certain single track block will not effect opposing signals farther ahead than the starting opposing signal to the single track block beyond the one which it is entering. 60 Applicant has not shown conducting controlling arm similar to 49 upon all of the signals as it is considered perfectly obvious to one skilled in the art that such construction may be employed if it is desired to fur- ther limit the extent of influence on opposing signals exerted by a train entering a single track block.

As hereinbefore explained, the entrance of a train onto the first track circuit section 70 as D¹ of a single track block immediately sets all opposing signals governing movements over that single track block at the stop position, therefore, it will be seen, that a train having once entered a block prevents 75 an opposing train from entering the same block, consequently, if a train is standing upon track circuit section A¹ and moves onto track circuit section D¹ before any opposing train moves from track circuit section B¹ onto track circuit section D⁶, it effectively prevents such second train from moving from track circuit section B¹ onto track circuit section D⁶. It is to be observed, 80 however, that as the train progresses through 85 the block, it clears the signals behind it successively in exactly the same manner as does a train when progressing in the direction of traffic upon a track-way, the movement of trains over which is governed by automatic signals, in other words, as soon as a train moving in one direction has secured possession of a single track block, that block and the signal governing movements of trains in the direction in which the assumed train 90 is moving is for all practical purposes a section of double track railway as far as following trains are concerned, so that after one train has entered the single track block 95 a following train approaching the single track block moving in the same direction as the train which precedes it, can move upon the single track block as soon as the entrance signal thereto moves to the caution position and it can do this with full assurance that it 100 will meet no train in the single track block traveling in a direction opposite to that which it is moving, furthermore, even should the first train proceed out of the single track block the second train which is already in 105 the block would act upon the signaling apparatus exactly as did the first train and would maintain the opposing signals at danger just as did the first train so that no train moving in an opposite direction could 110 enter upon the single track block.

In case a train moved onto a single track block and passed one of the intermediate signals, it could then back out of the block with perfect safety, if its movement was 120 governed by the position of the opposing signal, that is, in backing out of the block, its movements should be controlled by those signals on the opposite side of the track from those which gave it its right to enter into the block; for example: if a train should move from track circuit section A¹, through track circuit section D¹ and D² and D⁶ onto track circuit section D⁴ and it was then 125 found that the train should return to track 130

circuit section A¹, it could with perfect safety back as far as signal 4, for during all of the time that it is upon track circuit sections either D³ or D⁴ as hereinbefore explained, the train prevents signal 4 from moving from the full biased or danger position to either of the operative positions, and if upon reaching the insulating joints opposite signal 13, it was desired to continue the backward movement, the governing factor would be the position of signal 13. As heretofore explained signal 13 would move to the clear position as soon as such a train as we have considered, moved from track circuit section A¹ over track circuit section D¹ and D² entirely upon track circuit section D³, consequently, if no following train had entered upon track circuit section D¹, signal 13 would at least be in the caution position (as for example if a following train were in block C), and if no train were closer to signal 13 than the eastbound entrance to the single track block C, then signal 13 would be in the proceed position, consequently, the train could continue its backward movement toward siding A¹ and it would furthermore be protected in its backward movement by signal 3 in the danger position, because as soon as the train in its backward movement passed upon the rails of track circuit section D², it would deenergize track relay 27, thereby allowing armature 274 to fall and consequently, breaking the circuit of control relay 62, thereby deenergizing control relay 62 and thus allowing armature 271 to fall to its lower position interrupting the flow of current from battery 109 to both of the control wires for signal 3. The signal 3 would remain in the danger position during the time the train was upon track circuit section D² and as soon as the train passed upon the rails of track circuit section D¹, the track relay 26 would be deenergized and the circuit for control relay 62 would be broken at arm 270. If it was desired to continue the backward movement, it would be governed by signal 14 which would be either in a caution, proceed or danger position according to the position or presence of a train upon some part of the track-way between signal 14 and the entrance signals to single track block C at the passing siding next in the rear of passing siding A.

It should also be noted that the train just considered which backed from track circuit section D⁴ to track circuit section D¹, would, as soon as it passed entirely off from track circuit section D³ in its backward movement, establish a direction of movement for following trains, that is to say, the train by such movement would cause the signals to show such aspects as they would have shown if the train considered had moved from track circuit section B¹ through track circuit sections D⁶, D⁵, D⁴, D³ and D² onto track circuit section D¹, because as soon as the train backed from track circuit section D³ onto track circuit section D², control relay 65 for signal 12 would be energized by reason of the fact that stick relay 78 would be deenergized and stick relay 77 would be energized thereby allowing control relay 65 to obtain current through the following path: positive terminal of battery 110, wires 430, 431 and 432, arm 433, of pole changing switch 13¹, in the dotted line position due to the fact that signal 13 is in the danger position, wires 434, 284, 283, 435, 436 and 437, control relay 65, wire 438, armature 365, wires 439 and 440, armature 363, wire 441, armature 364, in the lower position because stick relay 78 is deenergized on account of control relay 64 being energized and armature 276 in the upper position, wires 442 and 443, armature 444, which is in the upper position because stick relay 77 was preliminarily energized and maintained energized by the passage of a train past signal 13 in the direction of movement governed by signal 13, wires 445, 446 and 447, arm of pole changing switch 448 in the dotted line position and wires 449 and 450, to the negative terminal of the battery 110. The current flowing in the above traced path to the control relay 65 would not be in the normal direction so armature 97 would be moved to the left but armature 355 would be in the upper position thereby allowing current to flow from battery 112 to the caution control wire 356 of signal 12 which would thereby be placed in the caution position, the signal 11, would also move to the proceed position due to the fact that control relay 65 is energized and armature 358 moved to the upper position, thereby completing a circuit in which current flows as follows: positive terminal of battery 112, wires 451, 452 and 453, arm 454 of pole changing switch 12¹ in the full line position as signal 12 is in the caution position, wires 455, 456 and 457, armature 358, wires 458 and 459, armature 367, wire 460, armature 366, wire 461, armature 368, wire 462, control relay 67, wires 463, 464, 465, 466 and 467, arm 468 of pole changing switch 12¹ in the full line position and wires 469 and 470 to the negative terminal of the battery 112. Current flowing in the above traced path and energizing control relay 67 would cause armature 99 to be moved to the right and armature 359 to be raised, thereby allowing current to flow from battery 114 to both the caution and proceed control wires 360 and 361, thereby causing signal 11 to move to the proceed position.

If it was desired to again change the direction of movement of the train which has heretofore been considered as backing from track circuit section D⁴ to track circuit section D¹ after reaching track circuit section

D¹ and again move in a same direction as when entering the block, it of course could proceed over track circuit section D² as far as signal 4 and it would find signal 4 in the 5 full clear position if no train had in the meantime entered the single track block D from the track circuit section B¹. Upon accepting the indication given by signal 4 and passing signal 4, all of the signals, re- 10lays and armatures would again assume the position which they formerly had when the train formerly passed from track circuit section D² onto track circuit section D³.

It will thus be seen that a train once having gained control of a block may move with perfect safety in either direction upon that block just so long as it moves according to the indication given by the signals, because if another train enters the single track block 20 while the first train is in the single track block, then the second train will maintain danger signals ahead of it just exactly as does the first train, and although the first train may reverse its movement it cannot 25 change the danger signals protecting the following train as long as the following train is upon the sections protected by the signals governing movements in a direction opposite to that in which the second train 30 is moving.

As has hereinbefore been explained, if a train is upon any part of single track block D moving in an easterly direction the signal 9 will be in a caution position. Such an 35 indication is employed so that any train moving in a westerly direction and passing signal 9, will never be deceived as to the position in which the signal 10 will be found on arriving thereat. If such indication were 40 not given, but instead a proceed aspect were given at signal 9, until signal 10 moved to the danger position, then it might be very possible that a train moving in a westerly direction could pass signal 9 in the proceed 45 position and then find signal 10 in the danger position, which would necessitate a severe application of the brakes because at the time the train passed signal 9, a train moving in an easterly direction might be 50 present upon the rails of track circuit section D⁵ and might immediately thereafter move upon the rails of track circuit section D⁶, which would as hereinbefore explained, immediately cause the signal 10 to move to 55 the danger position, and if the train which is moving in an easterly direction is progressing at a very high rate of speed it might well reach the extreme end of track circuit section B² before the west bound train received 60 the indication of signal 10, and the west bound train having received a proceed aspect at signal 9 would be running at such a speed as it would run if it had two full blocks clear ahead of it, consequently, it 65 might be running at such a speed that even

if the indication of signal 10 in the danger position were observed at the earliest possible moment, it would be impossible to apply the brakes with sufficient force to bring the west bound train to a stop in the available distance so that it would crash into the east bound train standing on the rails of track circuit section B². By causing signal 9 to have the caution position as soon as an east bound train enters upon single track 70 block D, the possibility of such an accident is obviated for, under such conditions the west bound train would always receive a caution indication upon passing signal 9, and therefore, the west bound train would 80 immediately be brought under control so it could be stopped at signal 10 without overrunning it.

It will be seen from the drawings that the system of circuits for the control of signals 85 for eastbound traffic is interlocked with the system westbound in that each stick relay (as 74) that functions for traffic one way (east) has an armature (228) in the line control circuit (for control relay 59) 90 that governs a signal (15) for traffic the other way (west). Among the advantages of this reciprocal check are that if a stick relay armature should stick after deenergization of the relay the signal to the rear 95 would remain as if the train were standing where this stick occurred, so that the defect is on the side of safety.

Although I have particularly described the construction of one physical embodiment of 100 my invention, and explained the operation and principle thereof, nevertheless, I desire to have it understood that the form selected is merely illustrative, but does not exhaust the possible physical embodiments 105 of the idea of means underlying my invention.

What I claim as new and desire to secure by Letters Patent of the United States, is:

1. In a railway signal system: a trackway 110 over which trains may move in both directions; insulating joints placed in the trackway at intervals forming sections; a translating device controlled by each section; signals governing the movement of trains over 115 said trackway in one direction; two signaling circuits for each signal; means controlled by all the translating devices controlled by a plurality of sections the entrance to which is controlled by separate signals for normally closing one of said circuits for a certain signal; means controlled by the entrance of a train when moving in the direction the signals govern into the track circuit section, the entrance to which is governed by a signal ahead of said certain signal, for closing the other signaling circuit and retaining it closed just so long as the train is in a section 120 the entrance to which is governed by said signal ahead. 125

2. In a railway signal system: a trackway over which trains may move in both directions; insulating joints inserted in said trackway at intervals forming sections; a translating device controlled by each section; a plurality of signals each governing train movements in one direction only; two signal circuits for each signal; one of the said signal circuits governed by the translating devices of the track sections between it and the next signal in the direction the signals govern, and the signaling circuits of said next signal in advance; a normally deenergized device; an energizing circuit for said device closed by the passage of a train in the direction the signals govern past said next signal in advance; a holding circuit for said device formed by the closing of the energizing circuit and the presence of a train on a track circuit section which the signal in advance governs; the other signaling circuit governed by said normally deenergized device, and by the translating devices governed by the track circuit sections which the signal in the rear of said signal in advance governs.

3. In a railway signaling system, in combination: a stretch of single track; a signal for governing traffic over a predetermined portion of said stretch; a signal circuit for said signal; a circuit controller responsive to the presence of a train in said predetermined portion of the stretch and open when that portion is occupied; a normally open shunt circuit for said circuit controller; means controlled by said signal circuit for closing said shunt circuit when a train travels in the direction of traffic governed by said signal and for holding said shunt circuit closed until said predetermined portion of the stretch is not occupied, said means preventing the closing of said shunt circuit when a train travels in the opposite direction; and means for signaling controlled jointly by said circuit controller and by said shunt circuit.

4. In railway signaling, a stretch of single track, signals located at intervals for governing traffic in one direction through the stretch and other signals located at intervals for governing traffic in the other direction through the stretch, a signal relay for the control of each signal, a circuit for each signal relay each of which circuits is controlled by the signal relay for the signal next in advance governing traffic in the same direction, track relays connected with the stretch for the control of the signal relay circuits, and means for rendering the signal relay for a signal in the rear of a car or train ineffective to control the signal relays for the signals in the rear which govern traffic in the same direction.

5. In combination, a stretch of railway track, over which traffic moves in both di-

rections, signals located at intervals for governing traffic in one direction through said stretch, a signal relay for the control of each signal, a circuit for each relay each of which circuits includes a contact of the relay for the signal next in advance, track circuits for the stretch including track relays for controlling said signal relay circuits, a branch for each signal relay circuit around the signal relay contact which controls such circuit, and means for controlling each of said branches.

6. In railway signaling, a stretch of single track, signals located at intervals for governing traffic in one direction through the stretch and other signals located at intervals for governing traffic in the other direction through the stretch, a signal relay for the control of each signal, the signal relay for each signal being controlled by the signal relay for the next signal in advance governing traffic in the same direction, track relays connected with the stretch for the control of the signal relays, and means for each signal relay for rendering said signal relay ineffective to control the signal relay for the next signal in the rear governing traffic in the same direction.

7. In railway signaling, a stretch of single track, signals located at intervals for governing traffic in one direction through the stretch and other signals located at intervals for governing traffic in the other direction through the stretch, a signal relay for the control of each signal, a circuit for each signal relay each of which circuits includes a contact of the signal relay for the next signal in advance governing traffic in the same direction, track relays connected with the stretch for controlling the circuits of the signal relays, a branch for each signal relay circuit around the contact of the signal relay which controls such circuit, and means for controlling each of said branches.

8. In railway signaling, a stretch of single track, signals located at intervals for governing traffic in one direction through the stretch and other signals located at intervals for governing traffic in the other direction through the stretch, a signal relay for the control of each signal, a circuit for each signal relay each of which circuits includes a contact of the signal relay for the next signal in advance governing traffic in the same direction, track relays connected with the stretch for controlling the circuits of the signal relays, a branch for each signal relay circuit around the contact of the signal relay which controls such circuit, auxiliary relays for the control of said branches, and circuits for the auxiliary relays controlled by the signal relays.

9. In combination, a stretch of single track, signals located at intervals for governing traffic in one direction through the

- stretch and other signals located at intervals for governing traffic in the other direction through the stretch, a signal relay for the control of each signal, each signal relay being controlled by the signal relay for the signal next in advance governing traffic in the same direction, track relays connected with the rails of the stretch for controlling the signal relays, and means for rendering the signal relay for a signal in the rear of a car or train ineffective to control the signal relay for the next signal in the rear governing traffic in the same direction.
- 15 10. In combination, a stretch of railway track, signals located at intervals for governing traffic through said stretch, a signal relay for each signal, means for controlling each signal relay by the signal relay for the signal next in advance, track circuits for the stretch including track relays for controlling said signal relays, and means for rendering each signal relay ineffective to control the signal relay for the signal next in the rear.
- 15 11. In combination, a stretch of railway track, signals located at intervals for governing traffic through said stretch, a signal circuit for each signal, means for controlling each signal circuit by the signal circuit for the signal next in advance, track circuits for the stretch including track relays for controlling said signal circuits, and means for rendering each signal circuit ineffective to control the signal circuit for the signal next in the rear.
- 15 12. In a signal system: a trackway composed of electrically independent sections; translating devices and sources of current, one of each connected to each section, thereby forming track circuit sections; signals at intervals along the trackway, the trackway between two successive signals forming a block; a circuit for each of said signals, each circuit including a circuit controller controlled by a translating device of the block controlled by the signal to which the circuit applies, and a circuit controller in each of the circuits for opening and closing that signal circuit in which it is placed, each of the last named circuit controllers controlled by a translating device of the block in advance of the block controlled by the signal to which the circuit containing said circuit controller applies; and means including a translating device of the block in advance to form a shunt around said last named circuit controller for said circuit when said last named circuit controller is open.
- 15 13. In a railway signaling system in combination: a semaphore; a second semaphore; a normally closed circuit for governing the first semaphore; a normally open circuit for governing the second semaphore; a trackway over which both said signals govern move- ments in the same direction; means dividing said trackway into a series of track circuit sections; means including a track circuit section for governing said first mentioned circuit; and means governed by the operation of the track circuit sections in one sequence only including a circuit controller governed by the normally closed circuit for closing the first normally open circuit.
14. In combination, a stretch of railway track, signals located at intervals through the stretch for governing traffic in one direction, and other signals located at intervals for governing traffic in the other direction, means controlled by a train in the stretch for causing all of the signals for the stretch to indicate danger, and means controlled by each signal while moving to danger as it is passed by a train for rendering said means ineffective to hold at danger the signals in the rear of the train governing traffic in the direction of movement of the train after the train has passed out of the portion of the stretch governed by the last-mentioned signals.
- 15 15. In combination, a stretch of railway track, signals located at intervals through the stretch for governing traffic in one direction, means controlled by a train in the stretch for causing all of the signals governing traffic toward said train to indicate danger, and means controlled by each signal while moving to danger as it is passed by a train moving in the direction in which traffic is governed by said signals for rendering said means ineffective to hold at danger the signals in the rear after the train has passed out of the portion of the stretch governed by the last-mentioned signals.
16. In combination, a stretch of railway track, a plurality of signals governing traffic in one direction through the stretch, a line relay for the control of each signal, a circuit for one of said line relays which circuit is controlled through the line relay of the next signal in advance, an auxiliary relay adapted when closed to shunt the last-mentioned line relay from its control of the signal in the rear, means controlled by a car or train passing along the stretch for closing said auxiliary relay, a signal governing traffic in the opposite direction through a portion of the stretch, and a circuit for said last-mentioned signal controlled by a back contact of the said auxiliary relay.
17. In combination, a stretch of railway track, two signals located at different points in said stretch for governing traffic through the stretch in one direction, a signal relay for each signal, a normally closed circuit for the signal relay for the forward signal, a normally open circuit for the signal relay for the rear signal, track circuits for the stretch including track relays for controlling said signal relay circuits, means includ-

- ing an auxiliary relay for closing said normally open circuit, a pick-up circuit for said auxiliary relay including a contact controlled by said normally closed circuit and a back contact of one of said track relays, and a holding circuit for said auxiliary relay including an armature contact thereof.
18. In a railway signaling system, in combination: a track divided into track circuit sections; a first signal and a second signal located at different points along the track for governing traffic in one direction; a signal circuit for each signal controlled by the track circuit sections protected thereby; means subjected to the same controlling influence as the signal circuit of the second signal for governing the signal circuit of the first signal; and means controlled by the signal circuit of the second signal and rendered effective by the entrance of a train, traveling in the direction in which said signals govern traffic, into a track circuit section adjacent to the second signal for preventing said first mentioned means from 25 producing a controlling effect on the signal circuit for the first signal.
19. In a railway signaling system, in combination: a track divided into track circuit sections; a first signal and a second signal located at different points along the track for governing traffic in one direction; a signal circuit for each signal controlled by the track circuit sections protected thereby; means subjected to the same controlling influence as the signal circuit of the second signal for controlling the signal circuit of the first signal; and normally inactive means rendered effective by the movement of a train in the direction of traffic governed by 40 said signals for nullifying the controlling effect of said means on the signal circuit for the first signal, said last mentioned means after being rendered effective being maintained in that condition until the signal circuit of the second signal assumes its normal condition.
20. In a railway signaling system, in combination: a track divided into track circuit sections each having a track relay; a first signal and a second signal located at different points along said track for governing traffic in one direction; means tending to cause the first signal to indicate stop when a train occupies the portion of track 55 protected by the second signal; normally inactive means for rendering said means ineffective; and a controlling circuit for said last mentioned means including a back point of the track relay of a track section adjacent to the second signal.
21. In a railway signaling system, in combination: a track divided into track circuit sections; a first signal and a second signal located at different points along the track 65 for governing traffic in the same direction;
- a signal circuit for the second signal controlled by the track circuit sections protected thereby; means tending to cause the first signal to indicate stop when a train occupies the portion of track protected by the second signal; and normally inactive means governed by said signal circuit for rendering said means ineffective, said last mentioned means being rendered effective by a train traveling in the direction of traffic governed by 70 said signals and entering a predetermined track circuit section adjacent to the second signal prior to entering another track circuit section in advance thereof which controls said signal circuit.
22. In a railway signaling system, in combination: a stretch of single track; a first signal and a second signal located at different points along the stretch for governing traffic in one direction; a signal circuit for each signal controlled by a train on the respective portions of the stretch protected thereby; a circuit controller included in the signal circuit of the first signal and subjected to the same controlling influence as the 80 signal circuit of the second signal, said circuit controller being opened when a train occupies the portion of the stretch protected by the second signal; a normally open shunt circuit for said circuit controller; an auxiliary electrically operable device for closing said shunt circuit when a train travels in the direction of traffic governed by said signals and for holding said shunt circuit closed so long as this train occupies said portion of 85 the stretch, said means automatically resuming its normal condition upon movement of said train out of said portion of the stretch.
23. In a railway signaling system, in combination: a stretch of single track divided into track circuit sections each having a track relay; a first signal and a second signal located at different points along said stretch for governing traffic in one direction; a signal circuit for each signal controlled by the track relays of the portion of the stretch protected thereby; a circuit controller for controlling the signal circuit of the first signal and responsive to the presence of a train 100 in the portion of the stretch protected by the second signal; a shunt circuit for said circuit controller; a second normally open circuit controller for controlling said shunt circuit; a device adapted to be controlled electrically for operating said second circuit controller; means including the track relay of a track section adjacent to the second signal for controlling the initial operation of said device; and means controlled by the 110 signal circuit of the second signal for maintaining said device in its operated condition after its operation has been initially determined.
24. In a railway signaling system, in com- 120

- bination: a stretch of single track divided into track circuit sections each having a track relay; a first signal and a second signal located at different points along the stretch for governing traffic in one direction; a signal circuit for the second signal controlled by the track relays of the portion of the stretch protected thereby; means tending to cause the first signal to indicate stop when the portion of the track protected by the second signal is occupied; means for rendering said means ineffective; an auxiliary relay for controlling said last mentioned means; an energizing circuit for said auxiliary relay controlled by said signal circuit.
25. In a railway signaling system, in combination: a stretch of track divided into track circuit sections each having a track relay; a first signal and a second signal; a signal circuit for each signal controlled by the track relays of the track sections protected thereby; a circuit controller governed by the signal circuit of the second signal and included in the signal circuit for the first signal; a normally open shunt circuit for said circuit controller; a stick relay for closing said shunt circuit when energized; an energizing circuit for said stick relay controlled jointly by a track relay of a track section adjacent to the second signal and by the signal circuit of said second signal; and a maintaining circuit for said stick relay controlled by the relay itself and by the signal circuit for the second signal.
26. In a railway signaling system, in combination: a stretch of single track divided into track circuit sections each having a track relay; a first signal and a second signal located at different points along the stretch for governing traffic in one direction; a signal relay for controlling each signal; a signal circuit for each signal relay; the signal circuit for the first signal including a front contact of the signal relay of the second signal; a normally open shunt circuit for said front contact; a stick relay for closing said shunt circuit when energized; a circuit controller governed by the signal relay of the second signal; an energizing circuit for said stick relay including said circuit controller and a back contact of a track relay adjacent to the second signal; and a maintaining circuit for said stick relay controlled by that relay itself and by the signal circuit of the second signal.
27. In a railway signaling system, in combination: a stretch of single track; a signal guarding the entrance to each end of said stretch; intermediate signals located along said stretch and governing traffic in both directions; means associated with each of said signals for causing it to indicate stop when the portion of track protected thereby is occupied; means associated with each intermediate signal and responsive to the presence of a train on the portion of the track protected thereby for causing the signal next in the rear to indicate stop; and means associated with each intermediate signal and rendered effective by a train traveling in the direction of traffic governed by that signal for rendering the corresponding last mentioned means ineffective.
28. In a railway signaling system, in combination: a stretch of single track divided into track sections; a source of current and a track relay associated with each track section; a signal guarding the entrance to said stretch at each end; intermediate signals located at intervals along the stretch for governing traffic in both directions; means responsive to the presence of a train in the stretch for causing all of the opposing signals ahead of that train to indicate stop; and means associated with each intermediate signal and selectively responsive to the direction of movement of a train for rendering said means ineffective as regards the signals located in the rear of that signal and governing traffic in the same direction.
29. In a railway signaling system, in combination: a stretch of single track divided into track circuit sections; signals guarding the entrance to said stretch; intermediate signals located at intervals along the stretch for governing traffic in both directions; means controlled by each track circuit section of the stretch and tending to cause all of the opposing and following signals on each side of that track circuit section to indicate stop; and means associated with each intermediate signal and selectively responsive to the direction of movement of a train for rendering said means associated with the track circuit sections protected by that signal ineffective to control the signals in the rear governing traffic in the direction of movement of the train.
30. In a railway signaling system, in combination: a stretch of single track; signals guarding the entrance to said stretch; intermediate signals located at intervals along the stretch for governing traffic in both directions; a signal circuit for each signal; means associated with each signal and responsive to the presence of the train in the portion of the stretch protected by that signal for controlling the signal circuit of that signal; means associated with each intermediate signal and subjected to the same controlling influence as its signal circuit for governing the signal circuit of the signal next in the rear governing traffic in the same direction; and means associated with each intermediate signal and selectively re-

sponsive to the direction of movement of trains for rendering the corresponding last mentioned means ineffective.

31. In a railway signaling system, in combination: a stretch of single track; a signal guarding the entrance to said stretch at each end; intermediate signals located at intervals along the stretch for governing traffic in both directions; a signal circuit for each signal; a source of current associated with each intermediate signal for supplying current to the signal circuit of the signal next in the rear governing traffic in the same direction; and means associated with each intermediate signal for controlling the connection between the corresponding source of current and the signal circuit of the next signal in the rear in accordance with the direction of movement of trains.
32. In a railway signaling system, in combination: a stretch of single track divided into track circuit sections; a signal guarding the entrance to said stretch at each end; two or more pairs of intermediate signals between the ends of said stretch for governing traffic in opposite directions; a signal circuit for each signal; means tending to control said signal circuits to cause all of said signals which are located between a given track section and either end of the stretch and which govern traffic toward said track section, to indicate stop when said given track section is occupied without affecting the other signals; and means associated with each intermediate signal and responding to the movement of trains in the direction of traffic governed thereby for rendering said means ineffective as regards the signals in the rear of that particular intermediate signal and governing traffic in the same direction.

33. In a railway signaling system a plurality of inter-controlled units for governing traffic in both directions; each of said units comprising a signal; a signal circuit for said signal; means controlled by said signal circuit for controlling the signal circuit of the unit next in the rear; and means selectively responsive to the direction of movement of trains for rendering said last mentioned means ineffective.

34. In a railway signaling system, in combination: a stretch of single track; signals located at intervals along the stretch for governing traffic in both directions; means responsive to the entrance of a train into said stretch for causing all of the opposing signals to indicate stop, said means permitting these opposing signals to successively indicate proceed as the train entirely passes them; and a plurality of means controlled by a train in the stretch in accordance with its direction of movement for causing the following signals to indicate stop as they are successively passed by said train.

35. In a railway signaling system, in combination: a stretch of single track; two sets of signals each comprising a signal at one end of the stretch and two or more intermediate signals for governing traffic in opposite directions over said stretch; means associated with each set of signals for causing each signal thereof to indicate stop when a train, traveling opposite to the direction of traffic governed thereby, occupies said stretch and to continue such indication until said signals are successively passed by that train; and means associated with each intermediate signal of each set for rendering said first mentioned means ineffective as regards the signals of that set in the rear when a train travels in the direction of traffic governed thereby.

36. In a railway signaling system, in combination: a stretch of single track divided into sub-blocks; signals guarding the entrance to each end of each sub-block; means responsive to the presence of a train in any sub-block for causing the signals guarding the entrance thereto to indicate stop; and means responsive to the direction of movement of a train entering any sub-block for controlling the signals of the adjacent sub-blocks in accordance with the direction of movement of said train.

37. In a railway signaling system, in combination: a stretch of single track divided into track circuit sections; sets of signals for governing traffic in both directions over said stretch; controlling means for each set of signals tending to cause each signal of that set to indicate stop when any track circuit section in advance thereof is occupied; a plurality of normally inactive controlling devices associated with each set of signals and operated only by a train traveling in the direction of traffic governed by these signals for limiting the controlling action of said corresponding controlling means upon each signal of that set to the track circuit sections directly protected thereby.

38. In a railway signaling system a plurality of inter-controlled units for governing traffic in both directions; each of said units comprising a signal, means tending to control the signal of the unit in the rear in the same way as the signal of the corresponding unit, and means responsive to the direction of movement of trains for rendering said last mentioned means ineffective at times.

39. In a railway signaling system, in combination: a stretch of single track; signals located at intervals along the stretch and governing traffic in both directions; the portion of said stretch between any two succeeding signals governing traffic in the same direction constituting a sub-block; means responsive to the presence of a train in any one of said sub-blocks for tending to cause

all of the opposing and following signals on each side of said sub-block to indicate stop; and a plurality of controlling devices associated with certain of said sub-blocks 5 and each rendered effective by a train traveling in a predetermined direction for limiting the control of said first mentioned means associated with that sub-block to the opposing signals in advance of the train and to 10 the next following signal in the rear.

40. In a railway signaling system, in combination: a stretch of single track divided into track circuit sections; signals located at intervals along the stretch and governing 15 traffic in both directions; means associated with each track circuit section and tending to cause all of the opposing and following signals on each side of that track circuit section to indicate stop; and a plurality of 20 means disposed at intervals along the stretch and each rendered effective by a train traveling in a predetermined direction for controlling the rear signals governing 25 traffic in that predetermined direction independently of said first mentioned means, whereby a train entering said stretch at an intermediate point after traveling in either direction far enough to cause operation of one of said last mentioned means will establish 30 its direction of movement and permit following train movements while blocking opposing train movements.

41. In a railway signaling system, in combination: a stretch of single track; a first 35 signal and a second signal for governing traffic in one direction; a signal circuit for the first signal; a source of current; means associated with the second signal and selectively responsive to the direction of movement 40 of trains for controlling the polarity and continuity of the connection between said source of current and said signal circuit, said means acting to disconnect said source of current from the signal circuit 45 when the portion of track protected by the second signal is occupied by a train which entered that portion traveling in the direction opposite to the direction of traffic controlled by said signal, said means also 50 changing the polarity of the connection between said source of current and said signal circuit when said portion of track is occupied by a train which entered that portion traveling in the direction of traffic controlled by said signals; and a polarized relay included in said signal circuit for controlling the aspects of the first signal. 55

42. In a railway signaling system, in combination: a stretch of single track; a signal 60 guarding the entrance to said stretch at each end; intermediate signals located at intervals along the stretch for governing traffic in both directions; a signal circuit for each signal; a source of current for each signal 65 circuit; and means associated with each in-

termediate signal for controlling the polarity and continuity of the connection between the corresponding source of current and the signal circuit of the signal next in the rear governing traffic in the same direction in accordance with the direction of movement of trains. 70

43. In a railway signaling system, in combination: a stretch of single track; a signal guarding the entrance to said stretch at each 75 end; intermediate signals located at intervals along the stretch for governing traffic in both directions; a signal circuit for each signal; a source of current for each signal circuit; pole changing means associated with 80 each intermediate signal and responsive to the flow of current in the signal circuit of that signal for controlling the polarity of the signal circuit of the signal next in the rear governing traffic in the same direction; and circuit controlling means associated with each intermediate signal and selectively responsive to the direction of movement of trains for controlling the continuity of the signal circuit for the signal next 85 in the rear governing traffic in the same direction. 90

44. In a railway signaling system, in combination: a stretch of single track; two signals located at different points in the stretch for controlling traffic in opposite directions; normally inactive means associated with each of said signals and rendered effective by the movement of a train in the direction of traffic controlled thereby; a signal 95 circuit for each signal; means associated with each signal for interrupting the signal circuit of the opposing signal when said corresponding means is in its effective condition; and other signals one in the rear of each of said signals for governing traffic in the corresponding direction and controlled by the corresponding normally inactive means. 100

45. In a railway signaling system, in combination: a stretch of single track; a signal for guarding the entrance to said stretch at each end; intermediate signals located at intervals along the stretch for governing traffic in both directions; a signal circuit for each signal; means associated with each intermediate signal and subjected to the same controlling influence as the signal circuit of that signal for governing the signal circuit of the signal next in the rear governing traffic in the same direction; normally inactive means associated with each signal for rendering said corresponding means ineffective upon movement of a train in the same direction as the direction of traffic governed thereby; and means operated by the change of each of said normally inactive means to its active condition for interrupting the signal circuit of the opposing signal in advance. 110

46. In a railway signaling system, in combination: a stretch of single track; a signal for guarding the entrance to said stretch at each end; signals located at intervals along 5 the stretch for governing traffic in both directions; a signal circuit for each signal; a device associated with each intermediate signal and controlled in accordance with the direction of movement of trains for controlling the signal circuit of the signal next in the rear governing traffic in the same direction; and means associated with each device for interrupting the signal circuit of the opposing signal in advance of the corresponding signal when that device is changed from its normal condition.
47. In a railway signaling system, in combination: a stretch of single track; a first signal and a second signal located at different points along the stretch for governing traffic in one direction; a third signal located in advance of these signals and governing traffic in the opposite direction; means tending to cause the first signal to indicate stop 25 when a train occupies the portion of the track between the second signal and the third signal; means rendered effective by the movement of a train in the direction of traffic controlled by the second signal for rendering said first mentioned means ineffective; and means for preventing the third signal from indicating proceed so long as said last mentioned means is in its effective condition.
48. In a railway signaling system, in combination: a stretch of single track; two signals for governing traffic in opposite directions over said stretch; normally inactive means associated with each signal and 30 changed to its active condition only by a train traveling in the direction of traffic governed by that signal; other signals controlled by said means, and means associated with each of said normally inactive means 35 and operated thereby preventing the other means being changed to its active condition so long as the first remains in its active condition.
49. In a railway signaling system, in combination: a stretch of single track; two signals for governing traffic in opposite directions; a normally deenergized stick relay associated with each signal; means for preventing the energization of either stick relay; 40 when the other stick relay is first energized; and other signals one in the rear of each of said two signals and governing traffic in the same direction; each of said other signals being controlled by the stick relay of the 45 corresponding signal in advance.
50. In a railway signaling system, in combination: a stretch of single track; two signals for governing traffic in opposite directions; a device associated with each signal and operated only by a train moving in one 55 direction; other signals controlled by said devices; a circuit for controlling the operation of each device; and means associated with each device for interrupting the effective operation of the other device when the first device is in its operated condition.
51. In a railway signaling system, in combination: a stretch of track; a first signal; two other signals located at different points in the rear of the first signal and governing 60 traffic in the same direction; means for causing the first signal to indicate stop; means for causing both of said other signals to indicate caution when a train traveling opposite to the direction of traffic governed by 65 said signals causes the first signal to indicate stop and for causing only the signal next in the rear of the first signal to indicate caution when a train traveling in the direction of traffic governed by said signals 70 causes the first signal to indicate stop.
52. In a railway signaling system, in combination: a stretch of single track with a passing siding at one end thereof; a first signal at the end of the passing siding remote from the stretch and governing traffic toward said stretch; a second signal in the rear of the first signal and governing traffic in the same direction; means tending to cause the second signal to indicate caution 75 when a train occupies said stretch; and means rendered effective by a train traveling in the direction of traffic governed by 80 said signals for rendering said means ineffective.
53. In a railway signaling system, in combination: a stretch of single track divided into blocks with passing sidings at the ends of said blocks; a signal located at a distance from each end of each block and governing traffic toward the siding at that end; and means for governing each of said signals in accordance with the direction of movement of the train in the adjacent block 85 in advance.
54. In a railway signaling system, in combination: a stretch of single track divided into track circuit sections and a passing siding extending part way along said stretch; a signal located at a distance from one end of this siding and governing traffic toward the siding; means controlled by a train in any one of a plurality of track circuit sections in advance of the signal and beyond the remote end of said siding for tending to 90 cause said signal to indicate caution; and means rendered effective by a train traveling in the direction of traffic controlled by said signal for rendering said last mentioned means ineffective.
55. In a railway signaling system, in combination: a stretch of single track divided into track circuit sections; a first signal and a second signal located at different points along the stretch for governing traffic in 95

- one direction; a signal circuit for each signal; means controlled by the next two track circuit sections in advance of the second signal for controlling the signal circuit thereof; 5 means controlled by one track circuit section in advance of the second signal for controlling the signal circuit of the first signal; and means rendered effective by a train traveling in the direction of traffic controlled 10 by said signals for rendering said last mentioned means ineffective.
56. In a railway signaling system, in combination: a stretch of single track divided into track circuit sections and a passing siding extending part way along said stretch; a first signal and a second signal located at opposite ends of said passing siding and governing traffic in the same direction; a signal circuit for each signal; means responsive to the presence of a train on a predetermined portion of the stretch in advance of the second signal for controlling the signal circuit of the first signal; and means rendered effective by a train traveling in the 20 direction of traffic governed by said signals for rendering said last mentioned means ineffective.
57. In a railway signaling system, in combination: a stretch of single track divided into blocks with passing sidings at the ends of said blocks; signals located at intervals along this stretch; some of said signals guarding the entrances to said blocks and others of said signals guarding the entrances to said sidings; means for causing the opposing signal guarding the entrance to a block to indicate stop when a train enters the block and for holding that signal at stop while said train occupies any portion 30 of the block; means for causing the signal guarding the entrance to a siding to indicate stop when a portion of the adjacent block in advance is occupied; and means operated by a train traveling in the direction 40 of traffic controlled by the last mentioned signal for rendering the corresponding last mentioned means ineffective.
58. In a railway signaling system, in combination: a stretch of single track; a signal guarding the entrance to said stretch at each end; intermediate signals located at intervals along the stretch for governing traffic in one direction; a polarized signal circuit for controlling each signal; means 45 associated with the signal circuit of each intermediate signal for controlling the continuity of the signal circuit of the signal next in the rear; means for rendering said last mentioned means ineffective; a circuit controller governed by the signal circuit of the first mentioned signal; means for establishing a shunt temporarily around said circuit controller upon interruption of the signal circuit for said first mentioned signal; and another signal in the rear of said 55 first mentioned signal and governing traffic in the same direction; and a controlling circuit for said another signal controlled by said circuit controller and said shunt.
59. In a railway signaling system, in combination: a stretch of track; a signal; a signal circuit for said signal; a circuit controller governed by said signal circuit; a second signal; a polarized signal circuit for controlling the second signal and including 70 said circuit controller; and means for establishing a shunt for said circuit controller temporarily upon interruption of the signal circuit for the first signal.
60. In a railway signaling system, in combination: a stretch of track; a first signal and a second signal for governing traffic in one direction; a polarized signal relay for the control of each signal; a signal circuit for each signal relay; means controlled 75 by the signal circuit of the second signal for controlling the signal circuit of the first signal; and means for temporarily rendering said means ineffective.
61. In a railway signaling system, in combination: a stretch of track; a first signal and a second signal for governing traffic in one direction; a polarized signal relay for controlling each signal; a circuit controller governed by the signal relay of 80 the second signal for controlling the signal relay of the first signal; and means for temporarily delaying the controlling action of said circuit controller upon deenergization of the signal relay of the second signal. 85
62. In a railway signaling system, in combination: a stretch of track; a signal; a polarized signal circuit for controlling said signal; a circuit controller governed by said signal circuit; a shunt for said circuit controller; slow acting means governed by said signal circuit for causing a temporary closure of said shunt upon interruption of said signal circuit; another signal; and a circuit for controlling the other signal governed by 90 said circuit controller and said shunt. 100
63. In a railway signaling system, in combination: a stretch of track, a signal, a control line circuit for said signal having two branches in multiple, a track relay controlling one branch, a stick relay controlling the other branch, and means dependent on the direction of traffic to energize said stick relay by a train movement in one direction 105 of traffic and not in the other direction. 115
64. In a railway signaling system, in combination: a stretch of single track railway, two signal systems to govern traffic in respective directions, stick relays and line circuits comprised in each system, means to energize the stick relays of each system only for the direction of traffic for which that system governs traffic, and normally closed circuit controllers in the line circuits for each direction of traffic adapted to be opened 120 125 130

by energization of the stick relays belonging to the system for the opposite direction of traffic.

65. In a railway signaling system, in combination: a stretch of track divided into track circuit sections, signals located at intervals along the stretch, a line relay and a stick relay associated with each such signal, line circuits for the line relays, each line circuit being controlled by a line relay or a stick relay alternatively, and means to energize the stick relays selectively for only one direction of traffic.

66. In a railway signaling system, in combination: a stretch of single track between passing sidings divided into track circuit sections, an absolute signal guarding the entrance to each end of the stretch, intermediate permissive signals located at intervals along the stretch for governing traffic in both directions, means including line circuits controlled by the track circuits for causing the stop control of each signal to extend ahead to the opposite end of the stretch, and normally inactive means associated with each intermediate signal and responsive to a predetermined sequence of operation of track circuits adjacent thereto for limiting the stop control of the next signal in the rear to the intervening track circuits.

67. In a railway signaling system, in combination: a stretch of single track, signals at intervals along said stretch for governing traffic in one direction, units of apparatus with the respective signals to control them, a line circuit from each unit to the unit in the rear, the line circuit of each unit being normally subjected to the same control as the line circuit of the unit next in advance, each unit comprising normally deenergized means which is adapted to independently energize the line circuit to the rear and which is selectively controlled according to the direction of movement of a passing car.

68. In a railway signaling system, in combination: a stretch of single track, signals at intervals along said stretch for governing traffic in one direction, units of apparatus with the respective signals to control them, a line circuit from each unit to the unit in the rear, each unit comprising a normally closed circuit controller for the line circuit to the rear and means to open said circuit controller for travel of a car either way and to apply opposite polarity and close a shunt around said circuit controller selectively for travel of a car in one direction only, and each unit comprising means further to control the associated signal according to the polarity of current in the circuit from the unit ahead.

69. In a railway signaling system, in combination: a stretch of single track between passing sidings divided into track circuit

sections, an absolute signal guarding the entrance to each end of the stretch, intermediate permissive signals located at intervals along the stretch for governing traffic in both directions, a line circuit for controlling each signal extending to the next signal in advance governing traffic in the same direction and controlled by the intervening track circuits, means associated with each intermediate signal and tending to control the line circuit of the signal next in the rear in the same way as its own line circuit is controlled, and normally inactive means associated with each intermediate signal and responsive to a predetermined sequence of operation of track circuits adjacent thereto for rendering said corresponding first mentioned means ineffective.

70. In a railway signaling system, in combination: a stretch of track, a signal, a control circuit therefor adapted to control the indications of the signal in accordance with the polarity and continuity of said circuit, said circuit having two multiple branches and respective controllers therein, a track relay governing one controller, a stick relay governing the other controller, means for causing said stick relay to become effective only for one direction of train movement, and means to reverse polarity on said control circuit at the time when the stick relay becomes effective.

71. In a railway signaling system, in combination: a stretch of track, two signals, one for each direction of travel, respective control circuits therefor, respective stick relays, means to actuate said stick relays selectively according to direction of train movement, and normally closed circuit controllers in the respective control circuits adapted to be opened by the oppositely associated stick relays.

72. In a railway signaling system, in combination: a stretch of single track between passing sidings divided into track circuit sections each provided with a normally closed track circuit and a track relay, two sets of successive signals at intervals through the stretch for governing traffic in opposite directions, control apparatus and circuits for each signal, line circuits extending between the successive signals of each set and controlled by the track relays of the intervening track circuits, and selective means at intervals throughout the stretch responsive selectively to the direction of movement of trains over track sections adjacent thereto, said control apparatus, line circuits and selective means coöperating under the influence of a single train at an intermediate point in the stretch to put the signals of both sets at clear for the movement of such train in either direction toward either end of the stretch, and to put at

stop all opposing signals in accordance with the direction in which such train traveled past the last selective means.

73. An automatic block signaling system for the stretches of track on single track railroads between passing sidings comprising, in combination, a signal guarding the entrance to the stretch of track at each end, a plurality of intermediate signals for governing traffic in both directions, and apparatus and circuits constituting means for controlling all of said signals, said means being influenced by the direction of travel of a train past any intermediate signal to cause those signals governing traffic away from such train in either direction to be clear, those signals at stop which govern traffic toward such train meeting its established direction of movement, and those signals at stop, caution, or clear, in accordance with their location, which govern traffic toward such train in the same direction as its established direction of movement.

74. In a railway signaling system, in combination: a plurality of track circuit sections each having a track relay; signal controlling line circuits controlled by the respective track relays and each line circuit controlled by another line circuit in sequential order; auxiliary signal controlling circuits; normally open circuit controllers in said auxiliary signal circuits; respective means controlled jointly by a corresponding line circuit and the track relay of a respective track circuit section for closing such circuit controllers when a train travels in one direction and occupies the corresponding track circuit section prior to occupying another track circuit section in advance thereof which controls the corresponding line circuit; said means also preventing the closure of such circuit controller when a train travels in the opposite direction and opens the corresponding line circuit prior

to occupying said corresponding track circuit section.

75. In a railway signaling system, in combination: a stretch of single track between passing sidings divided into track circuit sections, a signal guarding the entrance to the stretch at each end thereof, two sets of successive intermediate signals located at intervals through the stretch for governing traffic in both directions, control apparatus and circuits at each signal, a line circuit extending from each signal to the signal of the same set next in advance and controlled by the intervening track circuits, said control apparatus and circuits of each intermediate signal including means selectively responsive to the direction of movement of trains thereby and acting to establish an intercontrolling connection between its line circuit and the line circuit of the signal of the same set next in the rear when a train moves in the corresponding direction of traffic governed by such signals, and to discontinue such intercontrolling connection when a train moves in the opposite direction.

76. In a railway signaling system, in combination: a stretch of single track divided into track circuit sections, signals at intervals along the stretch for governing traffic in one direction, a polarized line relay for controlling the indications of each signal, a line circuit for each line relay extending to the next signal in advance and controlled by the intervening track circuits, means for controlling each line circuit from the line relay of the signal next in advance, and means for rendering said last mentioned means ineffective and for reversing the polarity of the corresponding line circuit.

SEDGWICK N. WIGHT.

Witnesses:

LILLIAN L. PHILLIPS,
LILLIAN M. MUTSCHLER.

It is hereby certified that in Letters Patent No. 1,294,736, granted February 18, 1919, upon the application of Sedgwick N. Wight, of Gates, New York, for an improvement in "Absolute Permissive Block-Signal Systems," an error appears in the printed specification requiring correction as follows: Page 22, line 45, claim 48, after the word "thereby" insert the word *for*; and that the said Letters Patent should be read with this correction therein that the same may conform to the record of the case in the Patent Office.

Signed and sealed this 8th day of April, A. D., 1919.

[REARL.]

F. W. H. CLAY,

Acting Commissioner of Patents.
